UNITED STATES PATENT OFFICE

2,482,458

ELEVATOR

Edgar M. Bouton, Nutley, N. J., assignor to Westinghouse Electric Corporation, East Pittsburgh, Pa., a corporation of Pennsylvania

Application June 25, 1945, Serial No. 601,388

47 Claims. (Cl. 187—29)

1

My invention relates to elevators and more particularly to high speed elevator systems designed for serving a plurality of floors in tall buildings.

In elevator systems of this character, it is customary to provide signal systems for indicating the position of the cars with reference to the floors and for indicating to intending passengers at the floors which car will stop for them, to provide control systems by which the cars may be started and stopped by switches or push buttons in the cars and in the floor landings, and to provide a floor selector for each car which will operate in response to movement of the car past the floors it serves for correctly connecting the signal and control circuits for such floors as the car approaches them.

One object of my invention is to provide an elevator with a control system, a signal system, and a floor selector therefor which shall be simple and inexpensive to construct, install and maintain in operation and which shall be more accurate in operation than those heretofore provided.

Another object is to provide an elevator system in which the floor selectors will not only connect the various signal and control circuits for the floors as the cars move from floor to floor, but will also automatically take care of the acceleration, running, deceleration and stopping of the cars in response to operation of the starting switches in the cars and the stop push buttons in the cars and at the floor landings.

Another object is to provide an improved control system for securing the most efficient operation of the hoisting motor without the necessity of personal attention by the car attendant.

Another object is to provide a signal and control system which will require relatively few electrical relays, and in which light pile-up contacts of the telephone type may be used instead of heavy contacts.

A further object is to provide a system in which most of the control and signal apparatus, together with the necessary wiring therefor, may be assembled with the floor selectors at the factory and be made ready for installation instead of having to assemble such apparatus individually in the penthouse or in the elevator hatchway at the time the elevator installations are made.

2

A further object is to provide a control and signal system for an elevator making an express run to an upper local zone in which the floor selector may be designed for only the upper zone without including parts which would otherwise be necessary for the floors included in the express zone as the car moves through that zone to the upper local zone.

A further object is to provide means for checking the position of the decelerating controller every time the car stops so as to ensure an accurate position of the controller for the initiation of the decelerating action at the next stop.

Another object is to provide an elevator system in which the speed of the car, as it slows down for a stop at a floor, is tied intimately to the position of the car as it slows down for that floor.

Another object is to provide an elevator system in which the means for controlling the speed of the car is operated directly by the floor selector.

Another object is to provide an elevator system in which the initiation of the slowdown of a car for a stop at a floor is made at a predetermined point as the car approaches that floor and in which the relation of the stationary and the moving parts of the floor selector determines such predetermined point.

Another object is to provide an elevator system in which the speed of the car during deceleration for a stop will be brought down to a predetermined value at approximately a given distance from the floor each time such operation takes place.

Another object is to provide an elevator system in which the slowdown of a car for a stop will be initiated at a point a predetermined distance from the floor at which the stop is to be made, and the initiation of the final slowdown operations of the selector will be made at a fixed distance close to the floor.

Another object is to provide a control means operated by a floor selector for decelerating a car to a stop at a floor and causing the control means to decelerate the car in coarse steps during the early part of the slowdown operation and for causing the control means to decelerate the car in fine steps during the final part of the slowdown operation as the car nears the floor.

Another object is to provide a leveling system

which will respond to one condition and operate in one manner when the car is being leveled to a floor during the stopping operation and which will respond to another condition in another manner for releveling the car if it leaves the floor while stopped thereat because of cable stretch or other conditions.

Another object is to provide an elevator control system in which a floor selector operated in accordance with the movements of the car is provided with means for actuating a control for the car motor which will be set into operation by a stop signal when the car approaches to within a predetermined distance of that stop signal and will be thereby operated to decrease the speed of the car in predetermined steps from its high speed to a relatively low speed by the time the car reaches a fixed distance from the floor, for initiating a final deceleration as the car reaches said fixed position which will be made in finer steps so that the car will softly and easily reach a very low stopping speed as it arrives closely adjacent to the floor level, and for then cutting off the power and applying the brake while the car is moving at such low stopping speed so that it will stop approximately level with the floor for which the stopping operation was initiated.

It is also an object to provide an elevator system in which the floor selector for the car and the means associated therewith for accelerating, running, decelerating, and stopping of the car may be operated by and in accordance with the movement of the car without any physical connection to the car.

Further objects of the invention will be obvious in the following description when taken in conjunction with the accompanying drawings, in which:

LIST OF RELAYS, ETC.

Individual to each car

- 45 7—emergency stop and pre-energization relay.
U—up direction switch.
D—down direction switch.
6—car running relay.
32T—control conditioning relay.
50 43T—leveling relay for controlling leveling for cable stretch.
UE—auxiliary up stopping relay.
DE—auxiliary down stopping relay.
H—clutch magnet control relay.
55 80—car starting relay.
22—auxiliary door relay—(starts doors opening).
45—door closing relay.
40—open-door safety relay.
W—up direction preference relay.
60 X—down direction preference relay.
65—auxiliary leveling relay.
TM—transfer brake magnet.
CM—clutch magnet.
GR4—speed relay.
65 GR6—speed relay.
GR8—speed relay.
GR6T—time accelerating relay.
GR8T—time accelerating relay.
UF—up leveling inductor.
70 DF—down leveling inductor.
T—torque reducer for advance motor (AM).
438—hall button stopping relay.
38R—no car call above relay.
DNP—pawl magnet coil on down selector carriage.

UPP—pawl magnet coil on up selector carriage.
78—high call reversal relay.
AM—advance motor.
CC—car button retaining coils.

Express zone relays

ER—express relay.
EI—express inductor relay.
ERX—express time delay relay.

DESCRIPTION OF FIGS. 1 AND 2

Referring more particularly to Figs. 1 and 2 of the drawings, I have illustrated an elevator system as embodying an elevator car A disposed for operation in a hatchway 9 at a normal high speed of approximately 800 feet per minute for serving eleven floors in a building, in which the floors are approximately ten feet apart. It is to be understood, however, that the invention may be applied to a car or a plurality of cars operating at any desired speed for serving any desired number of floors having various height ceilings, but it is believed that the system will be particularly useful for high speed cars serving a large number of floors or for express cars serving special groups of floors in the upper stories of tall buildings.

It should be understood further that all measurements, distances, etc., given in this description are given as examples of what may be used satisfactorily and are not to be taken as limitations in any sense, it being obvious that each installation will have to be designed to meet the conditions peculiar to that installation and that it will be necessary for the application engineer to modify the system where necessary to meet the conditions under which it is to be used.

Any desired number of cars may be added to the system described herein by adding control and signal circuits similar to the circuits for car A for each car, and connecting their hall call cancellation contacts to the cancellation coils, such as 2UN of the hall call registering relays (Fig. 22), as indicated by contacts such as B2U2.

The car is suspended on a hoisting cable 10 which passes over a hoisting drum 11 and around a traction sheave 12 to a counterweight 13. An electric motor 14 is provided for operating the hoisting drum 11 to raise and lower the car and a brake 15 is mounted on the frame of the motor for stopping the car after it is decelerated to stopping speed and for preventing its further movement in making a stop at a floor landing. A door 31 is disposed at each landing to permit entrance to the car.

A push button switch CS is mounted in the car for starting the car.

A plurality of suitable stop control devices, such as push buttons 2 and 3, one for each floor, are mounted in the car by which the attendant may cause the car to stop automatically at any floor at which a passenger desires to get off.

An up stop control device and a down stop control device, such as push buttons 2UB and 2DB, are mounted at each intermediate floor, with a single push button at each terminal, so that waiting passengers at the floor landings may press such buttons to cause the car to stop automatically for them. In starting the car, the attendant closes the car switch CS until the car starts to move and then opens it to place the car under control of the stopping buttons so that it will stop automatically at the floors in response to operated car buttons or operated hall buttons.

The car is provided with direction preference relays (to be described later herein) which cause it to continue in the direction in which it starts until it arrives at the terminal toward which it is moving where it is automatically reversed to travel to the opposite terminal. Hence, all the attendant has to do in operating the car is to press the car stop buttons as the passengers call their floors and press the starting button to restart the car after each stop is completed.

At times, it may be desirable for the attendant to reverse the car when it stops at some floor between terminals and an up direction push button UPB and a down push button DPB are mounted in the car for this purpose.

An up stopping and leveling inductor relay UF and a down-direction stopping and leveling inductor relay DF are disposed on a bracket 16 mounted on the car in position to cooperate with an inductor plate IP. The inductor plate is constructed of magnetic material and is mounted on the wall of the hatchway 9 in position to cooperate with and actuate contact members on the inductor relays when the relays are in an energized condition as the car approaches the floor at which it is to stop. I have shown an inductor plate for only one floor, but a similar inductor plate should be provided for each floor.

The inductor relay UF is provided with normally open contacts UF1 and the relay DF with normally open contacts DF1. The relays should be mounted on the bracket 16 with the contacts UF1 approximately 20% inches distant from the contacts DF1. The inductor plate IP should be approximately 19% inches long and should be so located on the hatchway wall adjacent the landing floor for which it is intended that it will be centered between the contacts UF1 and DF1 when the floor of the car is level with the landing floor.

An up signal device and a down signal device, such as a floor lantern 2LMU and a floor lantern 2LMD, are mounted at each floor landing to indicate to waiting passengers thereat when the car will stop for them and the direction in which it is traveling.

A floor selector mechanism 18 is associated with the car for connecting the various control and signal circuits of the car in accordance with its movement relative to the floors it serves and its direction of operation. Any suitable selector power means responsive to operation of the car may be used for operating the floor selector mechanism by the car in accordance with the movement of the car. As one example of such a suitable selector power means, I have illustrated a self-synchronizing drive embodying a motor SM operated by a synchronous generator SG which is connected to the shaft 19 of the traction sheave 12 by a pinion 20 and a gear wheel 21. For a more detailed description of the drive, reference may be had to J. F. Peters Patent

No. 2,130,899 issued September 20, 1938 for Remote control system.

DESCRIPTION OF FIG. 3

As illustrated in Fig. 3, the floor selector mechanism 18 includes the synchronous motor SM, a floor selector FS, a controller means such as a main controller M, and a leveling controller L, an advance motor AM, a first differential K1 operable by the synchronous motor and the advance motor for operating the floor selector, and a second differential K2 operable by the synchronous motor and the advance motor for operating the controllers.

The floor selector for connecting the various control and signal circuits of the car includes a plurality of sets of pile-up contacts such as 9U and 9D of the telephone type, for connecting the signal and control circuits for the various floors, an up carriage UC and a down carriage DC for operating the groups of contacts, and a chain drive 23 operated by the synchronous motor SM through the medium of a first differential K1 for moving the carriages up and down to operate the sets of pile-up contacts as the car moves from floor to floor. A safety slip clutch 24 is disposed between the synchronous motor SM and the differential K1 to prevent injury to the apparatus if the gears bind or the motor starts to burn up too much current.

The main controller M is provided for setting up time-controlled accelerating steps for the hoisting motor when it starts and, when the car is to be stopped, for decelerating the car in coarse steps from its normal high speed of, say, 800 feet per minute down to an intermediate speed of, say, 100 feet per minute.

The controller L is provided for continuing the deceleration of the hoisting motor in fine steps from the intermediate speed of say 100 feet per minute down to a low landing speed of say 10 feet per minute. In other words, the controller L acts as a vernier to reduce the speed of the hoisting motor, during the last stage of its deceleration, in such minute degrees as to enable the car to be brought softly and easily to a very low landing speed so that it will stop level with the floor when the hoisting motor is deenergized and the brake is applied. The leveling controller L is also used for controlling the hoisting motor in releveling operations.

A brake mechanism 25 and a clutch 26 are provided for sequentially rendering the controllers M and L operable through the differential K2. The brake mechanism includes a brake 27 for a first driven shaft or member 28 by which the differential K2 operates the controller L, a brake 29 for a second driven shaft or member 30 by which the differential K2 operates the controller M, and electromagnet TM for applying the brake 27 to the shaft 28 and a spring 32 for applying the brake 29 when the magnet TM is deenergized.

An electromagnet CM is provided for disengaging the clutch 26 and a compression spring 33 is provided for engaging the clutch when the clutch magnet is deenergized.

A pin 34 is attached to the operating arm of the clutch 26 for centering the controller M to its correct position each time it is returned to its "off" position.

The shaft of the advance motor AM is connected to the differential K1 for operating it to advance the floor selector carriages ahead of the car and to the differential K2 for operating it to

rotate the controllers M and L to their full "on" positions each time the car is started.

The shaft of the synchronous motor SM is connected to the differential K1 and is used for keeping the floor selector carriages moving after the car gets up to normal speed for rotating the controllers L and M from their "on" to their "off" positions when the car is to be decelerated to a stop. The acceleration of the car is controlled by time delay relays and its deceleration by the controllers.

DESCRIPTION OF FIGS. 4 TO 10 INCLUSIVE

As shown in the detailed drawings designated as Figs. 4 to 10, inclusive, the floor selector mechanism is provided with a main frame 35 comprising a plurality of vertical angle irons 36, 37, 38 and 39, a plurality of horizontal top angle irons 41, 42, 43 and 43a, and base angle irons 44, 45, 46 and 47. These angle irons are welded together at their joints to form a strong rectangular frame for supporting the floor selector FS, the motor controller M, the leveling controller L, the differential devices K1 and K2 and the motors SM and AM.

The floor selector FS has an auxiliary frame 49 constructed with a top plate 50 and a bottom plate 51 connected and spaced apart by a plurality of carriage guiding vertical rods 52, 53, and 54, a pair of contact supporting rods 55 and 56, and a pair of stop lug rods 57 and 58. The ends of the rods pass through the plates and are positioned and held firmly therein by a plurality of nuts 59.

The auxiliary frame 49 is mounted on the main frame by means of a topside hinge 60 and a bottomside hinge 61. The pivot end of the hinge 60 is rotatably mounted on the main frame by a hinge pin 62 disposed in a bracket 63 attached to an angle iron support 64 mounted on the vertical angle iron 37 of the main frame. The shank end of the hinge 60 is threaded on the vertical rod 56 and provided with an arm 66 which is firmly fastened to the top plate 50 by a pair of bolts 66a. A nut 59a is disposed on the rod 56 to hold the shank end of the hinge firmly against the top plate 51. The bottom hinge 61 is constructed and mounted adjacent to the bottom plate 51 in the same manner. The hinge mounting of the auxiliary frame permits it to be swung outwardly so that the carriages, pile-up contacts and chain drive may be easily mounted in position, inspected and maintained in good working condition.

A bracket 67 is seated on the rear central position of the top plate 50 and firmly held in that position by the nuts 59 on the upper ends of the rods 53 and 55. A pair of positioning bolts 68 and 69 are mounted on the upper portion of the bracket in position to impinge against the angle iron 43a in the main frame when the auxiliary frame is in its closed position. The bolts 68 and 69 may be rotated to adjust the position of the auxiliary frame against the main frame. A pair of holding bolts 70 and 71 are disposed beside the positioning bolts in the bracket so that they may be screwed into the angle iron 43a to hold the auxiliary frame in the position to which it is adjusted by the bolts 68 and 69. A similar bracket 72, with adjusting bolts and holding bolts, is mounted on the underside of the bottom plate 51 to engage the cross angle iron 44 when the auxiliary frame is in its closed position. When it is desired to have ready access to the apparatus on both sides of the auxiliary frame, the holding

bolts are screwed out of the angle irons and the frame is swung outwardly so that both sides may be readily examined.

Four blocks of pile-up contacts for each floor are mounted on the floor selector for connecting the signal and control circuits therefor. These blocks of contacts are given the reference characters P, U, S and D with a numeral prefix to indicate the floor with which they are associated. The individual pairs of contacts in each block are given the reference character for that block with a suffix number to distinguish it from the other contacts on that block. As an example, the P block for the 11th floor is marked 11P, and the pairs of contacts on it are marked 11P1, etc.

In looking at Fig. 7, we see the P and U blocks of contacts for the 11th floor and the S and D blocks of contacts for the 1st floor.

The group of pile-up P contacts for the 11th floor is designated as 11P and is mounted on the inner end of a strap-iron bracket 73, which is welded or otherwise secured to a U-shaped supporting bracket 74 disposed to embrace the contact carrying rod 55. A tapered bolt 75 is inserted through the ends of the bracket 74 to impinge against the rod and hold the bracket in any position on the rod to which it may be adjusted. The block of pile-up contacts 11P includes a pair of contacts 11P1 and a pair of contacts 11P2. The contacts are mounted on contact arms 76 and operating arms 77 disposed in a holding block 77a attached to the rear end of the strap support 73. The contact ends of the operating arms 77 are provided with operating blocks 79 disposed to be actuated by a main operating arm 88 on which is an operating button 81. The base end of the main operating arm 88 is attached to the supporting block 77a. When the button 81 is pressed outwardly, it causes the contacts 11P1 to close. A stop arm 82 is attached to the block 77a to limit the return motion of the main operating arm 88. The block of P contacts is disposed to be operated by the up carriage UC and its contacts, 11U1 are connected for operating indicator lamps (not shown), for indicating the position of the car in its hatchway, as shown for instance in Patent No. 2,085,135, issued June 29, 1937, on improvement in Position indicators by H. W. Williams.

The block of up pile-up contact devices 11U for the 11th floor is mounted on the outer end of the strap 73 and includes contacts such as 11U1, etc. This group of pile-up contacts is constructed in the same manner as the group P and is operable by a button 83 on an arm which moves outwardly on the up carriage when it is stopped as described later. The contacts on the U blocks of contacts for the various floors are used for lighting the up floor lanterns and for cancelling up stop calls at the floors when the car stops thereat.

The groups of pile-up contact members S are provided with individual pairs of contacts such as 11S3, etc., and are constructed in the same manner as the group of pile-up contacts 11P, but are mounted on the inner end of a strap-iron support 84. The strap support 84 is welded or otherwise secured to a U-shaped bracket 85 held by a tapered bolt 86 on the contact supporting rod 56. The pile-up contacts S are provided with an operating button 87, which, when operated, will open some of the contacts and close others.

The S contacts are operated by the down carriage DC and are used for connecting and opening circuits for the stopping relays to pick up stop calls and for the "call above" relay to determine when the car should reverse. For instance

the contacts such as 2S4 are closed each time the car approaches the 2nd floor and, if the car is moving upwardly and a stop call has been registered on the up hall button 2UB, the closing of the contacts 2S4 will pick up the call registered on relay 2UR and thereby cause the car to slow down and make an up stop at the 2nd floor.

The group of down pile-up contact devices 1D, which includes a pair of contacts 1D1 and a pair of contacts 1D2, is constructed in the same manner as the group 11P of pile-up contacts and is mounted on the outer end of the strap support 84 and provided with a button 89 which, when operated, will close both pairs of contacts. The contacts on the block 1D are operated by the down carriage DC and are used for lighting the down floor lanterns and for cancelling the down stop calls.

The contacts for any floor are spaced from the contacts for the next adjacent floors in accordance with the distance between the floors so that their position on the selector is a miniature reproduction of the distances between the floors served by the elevator. For instance, with a scale of one-eighth inch equals one foot for the spacing and the distance between the 10th floor and 11th floor is nine feet, the sets of pile-up contacts for the 10th floor will be disposed a distance of one and one-eighth inch from the pile-up contacts for the 11th floor.

The stop lug rod 57 carries a plurality of up stop lugs (Figs. 5 and 7), one for each floor. The up lugs are designated as 1UN for the 1st floor, 2UN for the 2nd floor, etc. The up lug 1UN embodies a projecting member 89 and may be securely fastened to the rod 57 by a pair of bolts 90 and a crossbar 91. The lug is placed on one side of the rod and the crossbar 91 on the other side so that by screwing the bolts through the bar and into the lug, the lug may be firmly seated at any desired point on the rod. The up lugs are used to stop the up carriage when the car, in moving upwardly, approaches a floor at which an up stop call is registered. The lug rod 58 is provided with a similar set of lugs for the down direction which are designated as 1DN, etc.

The stop lugs such as 2UN are spaced apart on the lug rods distances proportional to the distances between the floors, in the same manner as the sets of blocks of pile-up contacts are spaced apart and at points where they will stop the carriages in such positions that they will operate the contacts for the corresponding floors.

The up-carriage UC (Figs. 8 and 9) has a strap frame 95, bent somewhat in the form of the letter G. Two pairs of rollers wheels 96, 97, 98 and 99 are mounted on the top of the carriage frame by means of a wheel bracket 100 and a bolt 101. A similar set of wheels 102, 103, etc., is mounted on the underside of the lower end of the carriage frame by a wheel bracket 106 and a bolt 107.

The wheels 96 and 97 on the upper end of the carriage and the wheels 102 and 103 on the lower end of the carriage are disposed to impinge against or embrace the vertical carriage guiding rod 52 and the wheels 98, 99, etc., on the opposite side of the carriage are disposed to engage the rod 53, so that the carriage may slide up and down between the rods 52 and 53 with practically no friction.

A pawl arm 110 is pivoted on the carriage frame by a pin 111 disposed in a bracket 112 and a brace arm 113. The arm 113 is seated on the upper surface of the lower end of the carriage frame to which it may be welded or otherwise se-

surely fastened. The upper end of the pawl arm is bent at right angles to the pawl arm to form an armature 114 for the up pawl magnet UPP which is seated on the upper face of the lower part of the bracket arm 113 and held securely in position by the upper end of the bolt 107, which extends upwardly into the core 116 of the magnet. When the magnet is energized, by a stop call, it attracts the armature 114 and thereby moves the pawl arm 110 outwardly.

A tension spring 118 is connected between an arm 119 on the lower end of the pawl arm 110 and a rod 120 depending from the lower end of the carriage frame. The spring biases the pawl arm to its normal innermost position with the armature 114 away from the pawl magnet UPP.

A pawl wheel 121 is rotatably mounted in the lower end of the pawl arm in position to engage one of the stopping lugs on the rod 57 and stop the carriage when the pawl arm 110 is moved outwardly by the car picking up a stop call.

A block UP of pile-up contacts such as UPP1, UPP2 and UPP3, similar to the pile-up contacts already described, is mounted on the rear face of the carriage frame and provided with an operating button 123 disposed in a slot 124 in the frame in such position as to be engaged and operated by a wheel 125, mounted in a bracket 126 on the upwardly bent end 127 of the armature 114 when the magnet UPP is energized. When the wheel 125 strikes the button 123, it closes the contacts UPP1, UPP2 and UPP3. These contacts provide self-holding circuits for the pawl magnet and for energizing the torque reducing relay T for the motor AM.

A downwardly extending plate 129 (Fig. 8) is attached to the rear face of the carriage frame to provide a seat for a terminal block (not shown) for the conductors included in the cable 130 (Fig. 5) leading from a terminal block 128 to the contacts and electromagnet on the carriage. The cable 130 is flexible and trails up and down with the carriage.

The down-carriage DC is mounted on the carriage guiding rods 53 and 54 and is constructed in the same manner as the up-carriage UC and is provided with a block of pile-up contacts DNP1 and DNP2 similar to the block of UPP pile-up contacts on the up-carriage UC. The electromagnet DNP is mounted on the down carriage in position to operate its armature 131 and its pawl arm 132 on which is a pawl wheel 133.

The chain drive 23 for moving the carriages up and down in accordance with the movement of the car past the floors it serves comprises an upper chain section 135 which passes over a driving sprocket wheel 136 and a lower chain section 137 which passes under an idler sprocket wheel 138. One end of the upper chain section 135 is fastened to an eye 139 in the upper end of the bolt 101 disposed in the top of the carriage UC, and its other end is fastened in a similar manner to the down-carriage DC. One end of the lower chain section 137 is fastened to an eye 140 in the bolt 107 disposed in the lower end of the frame of the up-carriage UC, and its other end is secured to the lower end of the down-carriage DC in a similar manner. With this chain construction, the rotation of the driving sprocket wheel 136 for the up direction will cause the up-carriage to move upwardly and the down-carriage to move downwardly. Rotation of the driving sprocket 136 for the down direction will cause the down-carriage DC to move upwardly, and the up-carriage UC to move downwardly.

A contact operating wheel 143 is rotatably mounted on the pawl arm 110 of the up-carriage for operating the blocks of pile-up contacts U, 2U, etc. When the pawl magnet UPP is energized by a stop call, its armature 114 will move the pawl arm 110 outwardly and thereby move the contact wheel 143 into engagement with the actuating button 83 on the group of U-contacts for the floor at which the stop is to be made and thereby close the U contacts for that floor. Hence, the U-contacts for a floor will be closed only when the pawl magnet is actuated for a stop at that floor. As long as the pawl magnet is not energized, the wheel 143 rides up and down with the carriage without touching the buttons 83 on the blocks of U-contacts for the various floors.

The lower part of the frame 95 of the up-carriage UC is extended in the form of a bracket 144 to support a pair of rotatable wheels 145 and 146 for engaging the buttons 81 on the blocks of P-contacts as the carriage moves up and down. Inasmuch as one pair of contacts in the P-block is for lighting the lamps in the floor position indicator, and at least one of the lamps should remain lighted all the time to indicate the position of the car, a shoe 147 is associated with the wheels 145 and 146 to maintain pressure on the button 81 for one floor until the carriage gets to the button 81 for the next floor, and thus cause the position lamp for the next floor to be lighted just as the position lamp for the previous floor is extinguished.

The down-carriage DC is provided with a contact wheel 149 on its pawl arm 132 for operating the contact button 86 on the D block of contacts associated with the down-carriage. The wheel 149 normally remains out of engagement with the contact buttons 89 as the carriage moves up and down, but when the down pawl magnet DNP is energized, its pawl arm 132 moves the wheel 149 outwardly to engage and operate the button 89 for the block of pile-up contacts for the floor at which the car is to stop.

A pair of wheels 150 and 151 are rotatably mounted on bracket arms 141 and 142 (Fig. 10) attached to the lower end of the frame of the down carriage DC for operating the buttons 87 on the S-blocks of pile-up contacts as the carriage moves up and down. The wheels 150 and 151 are mounted in fixed staggered positions to operate the S-blocks of contacts for each floor each time the car passes that floor. The staggered position of the wheels causes engagement of the floor pile-up contacts S approximately $\frac{3}{8}$ " ahead of the final pawled position of the carriage to operate the call pickup and high call reversal contacts for each floor.

A casing 152 for housing the differential K1, through which the floor selector FS is operated, is mounted on the rear face of the floor selector mechanism frame 35. The casing 152 is disposed on a supporting plate 153 which is attached to the frame 35 and to an angle iron 154 on the top of the frame by a plurality of bolts 155. A collar 156 is used on each bolt to space the plate 153 apart from the frame 35.

The driving sprocket 136 of the chain drive 23 is fixed on the outer end of shaft 157 rotatably mounted in the frame 35 and extending therethrough to a coupling 158 by which it is attached to the outer end of a shaft 159, the inner end of which extends into the casing 152 for connection to the output member or shaft 217 of the differential K1 therein.

The casing 152 also covers the differential K2

through which the controllers M and L are operated.

The motor controller M and the leveling controller L are mounted on the rear face of the frame 35 in side-by-side relation underneath the casing 152 by means of a supporting plate 160 and a plurality of bolts 161 and brackets 162.

The motor SM is mounted on a top plate 163 disposed on the top of the frame 35, and its shaft 164 is connected by the slip clutch 24 to a shaft 165 which extends into the casing 152 and is connected by gears to the input member or shaft 212 of the differential gear K1 so that operation of the motor will operate that differential.

The advance motor AM is also mounted on the motor support plate 163, and its shaft 166 is connected by a coupling 167 to a shaft 168 which extends into the casing 152 for connection by gears to the input-output member or gear 226 of the differential K1 and to the driving member 236 of the differential K2.

CONTROLLERS M AND L IN FIGS. 11 AND 12

The controller M has a body comprising a back plate 170, a bottom plate 171, a top plate 172, a rotatable drum shaft 173 and a covering casing 174. A bottom brace plate 171a and a top brace plate 172a are mounted on the back plate 170 in position to support and maintain the bottom plate and the top plate in their correct positions. The lower end of the drum shaft 173 is seated in an end-thrust bearing 175 mounted in the upper face of the lower plate. The upper end of the drum shaft 173 extends upwardly through the top plate 172 to an end-thrust bearing 176 (Fig. 16) in the brake drum 29a of the brake 29 on the shaft 30 of the differential K2.

A plurality of up-contacts, such as M1U, are mounted on the back plate 170 at one side of the controller shaft and a plurality of down-contacts, such as M1D, are mounted on the back plate at the other side of the controller shaft in position to be operated by a plurality of cams, such as 179, fixed on the drum shaft.

A plurality of up-contacts, such as M6U, are mounted on the back plate at one side of the controller shaft and a plurality of down-contacts, such as M6D, are mounted on the back plate at the other side of the controller shaft in position to be operated by a plurality of cams, such as 180. The cams 180 are provided with adjustable screws 181 by means of which they may be adjusted to operate the contacts as desired.

A stop member 182 is fixed on the lower end of the drum shaft in such position that the drum will be stopped by an up direction adjustable limit device or lug 183 when it rotates for up direction and by a down adjustable limit device or lug 184 when it rotates for down direction. The drum is shown in its neutral center or "off" position from which it may be rotated a maximum of 150° to its "on" position for either direction of operation of the car. The movement from "off" to "on" is the equivalent of or takes place while the car is moving approximately 20 feet, that is, the controller will be rotated 150° from an "on" to its "off" position in decelerating the car through a distance of 20 feet.

The limit lugs 182 and 184 are adjustably mounted on the underside of the bottom plate 171 by machine screws 183a and 184a so that they may be adjusted to limit the angular movement of the controller drum to any desired degree. As illustrated, they are set to limit the rotation of the drum from its center position to

150° in either direction, in order to accord with the operation of the car at a normal high speed of 800 ft. per minute.

For a low speed installation of 350 ft. per minute, the limit lugs may be adjusted to stop the drum when it turns 75° so that the floor lantern lead will be $\frac{3}{4}$ of a floor, the carriage lead will be $\frac{3}{4}$ of a floor and the slow down distance will be $\frac{3}{4}$ of a floor. This occurs because the limited movement of the controller limits the amount of resistance in the generator field winding and stops further rotation of the advance motor and hence a further increase in the lead of the carriages over the car. If the limit stops are set for 130°, the floor lantern lead and the slow down distance will be $1\frac{1}{2}$ floors. Hence, adjustment of the lantern lead, the stopping distance and the speed of the car may be effected by one simple adjustment of the limit lugs on the decelerating controller.

The contacts embodied in the controller are of the usual type biased to open position by springs (not shown) and closed by the action of the cams as the disks are rotated, in the manner illustrated and described in the Williams and Ellis Patent No. 2,094,337, dated September 28, 1937.

The used contacts on the controller M are as follows:

30	M1U	Contacts on controller for short circuiting resistor sections R8, R7, R6 and R5 during up deceleration.
35	M1D	
	M2D	Same for down.
	M3D	
	M4D	
40	M5U	for energizing GR4 to short R4 in up direction acceleration.
	M6U	for preparing GR6 for energization by GR6T1 to short R3 in up direction deceleration.
45	M7U	for preparing GR8 for energization by GR8T1 to short R2 in up direction deceleration.
	M5D	for energizing GR4 to short R4 in down direction deceleration.
50	M6D	for preparing GR6 for energization by GR6T1 to short R3 in down direction deceleration.
	M7D	for preparing GR8 for energization by GR8T1 to short R2 in down direction.
55	M13U	for inserting resistor R14 in circuit of advance motor AM in up direction deceleration.
60	M13D	for inserting resistor R14 in circuit of advance motor AM in down direction deceleration.

The other contacts on controller M are spares which may be used for interlocking more points of spaced control, etc.

65 The controller L is constructed with a back plate 185, a bottom plate 186, a top plate 187, a rotatable drum shaft 188 and a casing 189. A lower brace plate 190, and an upper brace plate 191 are mounted on the back plate 185 in position to brace the bottom plate and the top plate. The lower end of the drum shaft 188 is mounted in an end-thrust bearing 192 in the bottom plate and its upper end in an end-thrust bearing 193 in the top plate. The drum shaft 188 extends upwardly to a point where it is connected by a

coupling 194 (Fig. 13) with the shaft 28 connected to the differential K2.

A plurality of up-contacts, such as L1U, are mounted in the upper part of the controller on the brace plate 185 at one side of the shaft 188 and a plurality of down-contacts, such as L1D, are mounted on the back plate at the other side of the shaft 188 in position to be operated by a plurality of cams, such as 195. These cams are fixed on the drum shaft to rotate with it as it is turned. 5 10

A plurality of up-contacts, such as L9U, are mounted in the lower part of the controller on the back plate 185 at one side of the drum shaft 188, and a plurality of down-contacts, such as L9D, are mounted on the back plate at the other side of the drum shaft in position to be operated by a plurality of cams, such as 196. These cams may be adjusted to any desired position by means of setscrews 197 disposed in their collars. The drum is shown in its neutral center or "off" position from which it may be rotated 150° in either direction to its "on" position for that direction. The 150° movement of the controller is equal to approximately a 20-inch movement of the car; that is, the controller will be rotated 150° in decelerating the car a distance of 20 inches.

A stop lug 198 is mounted on the shaft 188 in position to strike a limit lug 199 when the controller is moved to its "on" position for down operation or a limit lug 199a when rotated to its "on" position for up operation. The limit lugs are adjustably mounted on the underside of the plate 186 to permit an angular movement of the drum for 150° from neutral in either direction (see Fig. 12).

The used contacts on the controller L are given the following reference numerals:

L1U } For inserting resistors R9, R10 and R11
L2U } in generator field GF during up direc-
L3U } tion deceleration.

L1D For inserting resistors R9, R10 and R11
L2D in generator field GF during down direc-
L3D tion deceleration.

L9U } For energizing auxiliary door relay 22 to
L9D } start opening doors when car is nine
      } inches from stop.

L11U } For energizing brake transfer magnet TM.
L11D }

L12—for preparing the advance motor AM for operation in starting before doors close.

The other contacts on controller L are spares which may be used for other purposes, such as interlocking more points of speed control, etc.

DESCRIPTION OF DIFFERENTIALS K1 AND K2 IN
FIGURES 13 TO 18 INCLUSIVE

The differential K1 is connected for operation by the synchronous motor SM, through the shaft 165, which extends from the motor and into the casing 152 in which it is seated in a bearing 200 attached to the plate 153 and in the bearing 201 disposed in the outer end of a bracket 202, the inner end of which is also seated on the plate 153. A bevel gear wheel 203 is fixed on the shaft 165 in position to engage and operate a bevel gear 204 fixed on the end of a shaft 205 which is rotatably mounted in a pair of brackets 206 and 207, forming part of an overall bracket 208 attached to the back wall 153.

A worm gear 210 is fixed on the shaft 205 in position to engage and operate a worm wheel 211.

seated on a shaft 212 rotatably mounted in the central portion of the main bracket 208, so that rotation of the input shaft 212 will be effected when the synchronous motor SM is operated. A synchronous motor drive gear wheel 213 is fixed on the lower end of the drive shaft 212 in position to engage and mesh with a pair of differential pinions 214 and 215 both of which are disposed to mesh with a differential gear wheel 216 fixed on the upper end of the output shaft 217 seated in the upper portion of a bracket 218, mounted on the back plate 153.

A bevel gear wheel 218 is fixed on the lower end of the shaft 217 in position to mesh with a beveled gear wheel 220 fixed on the shaft 159 by which the sprocket wheel 136 is operated. The shaft 159 is rotatably mounted in bearings 221 and 222, disposed in the lower ends of the bracket 218 mounted on the plate 153.

20 The differential pinions 214 and 215 are rotatably mounted on a differential pinion shaft 223, the outer ends of which are fixed in a pair of brackets 224 and 225 fixed on the underside of the input-output member or gear body 226 to constitute a cage for the differential parts. The gear body 226 is rotatably supported on the shaft 212 and is provided on its outer periphery with an interconnecting drive gear 227 disposed to mesh with a pinion 228 associated with the connection between the advance motor AM and the differential K2.

The shaft 166 connected to the shaft of the motor AM for influencing the operation of the differential K1 and K2 and extending into the casing 152 is rotatably mounted in a bracket 230 forming a part of the overall bracket 208 attached to the back plate 153. A beveled gear wheel 231 is fixed on the shaft 166 in position to mesh with and operate a beveled gear wheel 232 fixed on the upper end of a shaft 233 rotatably mounted in the outer ends of a bracket 274 mounted on the back plate 153. A spur gear wheel 235 is fixed on the lower half of the shaft 233 in position to engage the driving pinion 228 which is fixed on 40 the driving shaft or member 236, rotatably disposed in parallel with the shaft 233 in the bracket 224.

The shaft 230 extends downwardly below the bracket 234 and an advance motor drive gear 50 wheel 237 is fixed on its lower end in position to mesh with a pair of differential pinions 238 and 239 both of which are disposed to mesh with a differential gear wheel 240 fixed on the upper end of a shaft 241 rotatably mounted in the outwardly extending arms 242 and 243 of a main bracket 244 bolted to the back plate 153.

The differential pinions 238 and 239 are rotatably mounted on a differential pinion shaft 245, the outer ends of which are fixed in a pair of brackets 246 and 247 mounted on the underside of a gear body 248 which is rotatably disposed on the shaft 236 above the drive gear wheel 237. The pinion shaft, the brackets and the gear body serve as a cage for the gears in the differential.

A spur gear wheel 250 is rotatably mounted on the lower end of the shaft 241 in position to mesh with and operate a spur gear wheel 251 mounted on a shaft 252 rotatably disposed in a bearing 253 mounted on the main bracket 244. The gear wheel 251 is disposed to mesh with and operate a spur gear wheel 254 fixed on the upper end of the brake shaft 30 which is rotatably disposed in a bearing 258 on the main bracket 244. The second driven shaft 30 is connected by the

clutch 26 to the drum shaft 173 of the controller M. When the gear body 248 is prevented from rotating and the advance motor AM is rotated, the controller M will be rotated, providing the brake 29 is released and the clutch 26 is effective. 5

The periphery of the gear body 248 is provided with a gear wheel 258 disposed to mesh with a gear wheel 259 fixed on the upper end of a shaft 260, rotatably mounted in a bearing 261 supported on the upper arm 262 of a portion of the main bracket 244. A gear wheel 263 is fixed on the lower end of the shaft 260 in position to mesh with and operate a pinion 264 fixed on the upper end of a shaft 265 rotatably mounted in the outer ends of the bracket 262. A gear wheel 266 is fixed on the lower end of the shaft 265 in position to mesh with and operate a pinion 267 fixed on the upper end of a shaft 268 rotatably mounted in a bearing in the lower arm of the bracket 262. The shaft 268 is connected with the upper end 20 of shaft 28, the lower end of which is connected by the coupling 194 to the controller shaft 188 for operating the leveling controller L. The shaft 28 is rotatably mounted in and end-thrust bearing 269 disposed in a bracket 270 attached to the back plate 153.

When the controller M is locked and its shaft 173 is prevented from rotating, rotation of the shaft 236 by either the advance motor AM or the synchronous motor SM will cause operation of the leveling controller L.

The brake 27 on the leveling controller shaft 188 and the brake 29 on the controller M shaft are mounted on the outer ends of a brake lever 273, the center of which is pivotally supported by a pivot pin 274 mounted in a bracket 275 disposed on the back plate 153.

The brake 27 includes a brake drum 27a which is fixed on the shaft 28 in position to be engaged by a brake shoe 27b seated on one end of the brake lever 273.

A pull rod 276 connects the end of the brake lever 273 bearing the brake shoe 27b to the brake transfer magnet TM. The rod is slidably disposed in a bracket 277 on the back plate 153 and its outer end is pivotally connected to the bifurcated end 278 of the brake lever 273 by a pivot pin 279, while its inner end may be connected to the magnet in any suitable manner. A nut 276a is adjustably disposed on the rod 276 to limit its movement. When the magnet is energized, it pulls the rod 276 and thereby applies the brake 27 to stop rotation of the shaft 28 and, hence, the drum shaft 188 of the controller L.

The brake 29 comprises a brake drum 29a, fixed on the lower end of the shaft 30 in position to be engaged by a brake shoe 29b mounted on the other end of the brake lever 273.

The compression spring 32 for applying the brake 29 is disposed on the outer end of a rod 282 between a nut 281 and the outer face of the brake lever. The inner end of the rod 282 is held in the back plate 153 by a nut 283.

The clutch 26 for connecting the controller M to the differential K2 comprises a friction member 284 slidably disposed on the upper end of the drum shaft 173 in position to enter and engage the conical inner face 285 of the brake drum 29a. A sliding key 286 prevents the friction member 284 from rotating on the shaft 173. The compression spring 33 for engaging the clutch members is held in compression between the lower end of the clutch drum 284 (Fig. 16) and a pair of nuts 287 disposed on the drum shaft 173. The compression of the spring 33 should be so ad-

justed by the nuts 287 that the clutch will not slip when it is engaged with the brake drum 29a.

The electromagnetic coil CM for releasing the clutch 26 is mounted in a casing 288 which is attached to the inner side of the back plate 153 by a plurality of bolts 289. The clutch magnet is provided with a push rod 290, the upper end of which is pivotally connected by a link 291 to one end of a clutch lever 292, the other end of which is bifurcated and pivotally disposed on a pin 293 seated in the outer ends of bracket arms 294 and 295, the inner ends of which are mounted on the outer surface of the plate 153. A pair of rollers 296 and 297 are rotatably mounted on the inner sides of the bifurcated end portion of the lever 292 in position to extend into an annular slot 298 around the shank of the clutch member 284.

When the magnet CM is deenergized, the clutch spring 33 forces the clutch member 284 into engagement with the inner clutch face 285 of the brake drum 29a so that rotation of the differential shaft 30 will rotate the shaft 173. When the magnet CM is energized it pulls downwardly on the inner end of the lever 292 and thus causes the rollers 296 and 297 to engage the lower collar on the groove 298 and thereby force the clutch member 284 downwardly out of engagement with clutch face of the brake drum 29a so that the brake drum 29a and the shaft 30 may rotate independently of the controller shaft 173.

A tension spring 299 is connected to the upper end of the link 291 and to the outer end of a projecting bolt 300 mounted in the back plate 153 for balancing the upward motion of the link 291 and pin 34 when the magnet CM is deenergized. The tension spring supports the weight of the plunger and the linkage associated with it and also acts as a biasing spring to hold the rollers 296 and 297 against the upper side of the groove 298 in the clutch shank and thus insure accurate operation of the clutch.

The pin 34 for centering the controller drum shaft 173 of the controller M when it is moved to its neutral or "off" position is slidably disposed in a bracket 301 attached by suitable machine bolts to the outer face of the back plate 153. The upper end of the centering pin is pivotally connected by a link 302 to the central portion of the clutch lever 292 by a pin 303 so that operation 50 of the clutch magnet CM to release the clutch 26 when the controller reaches its full-off position, will move the center pin 34 downwardly to cause its cone-like point to enter a cone-like hole 304 (Fig. 5) in a centering plate 305 which is fixed on the drum shaft 173 of the controller M. If the controller is slightly out of its correct alignment for the next operation, the entry of the centering pin into the centering hole 304 will, by its cam-like action on the centering plate, rotate the controller shaft 173 to its correct center position. This centering action takes place every time the car is stopped at a floor to correct for cable creep and slippage.

65 DESCRIPTION OF FIGS. 19 AND 20—DIAGRAM POSITION OF CONTROLLER CONTACTS

Fig. 19 gives a diagram or chart of the sequence of the closing and opening of the drum contacts on the controller L. The full lines in the diagrams represent the closed position of the contacts in accordance with the angular position of the drum. The figures 7", etc., in the upper margin represent the distance the car moves in 70 rotating the drum and the figures given in the 75

lower margin such as 45° indicate the angular motion of the drum.

For instance, the line opposite L3D indicates that the contacts L3D are closed during movement of the controller from its 150° position to its 135° position by the car while the car decelerates downwardly from its position 20 inches from the floor to its position 18 inches from the floor at which it is to be stopped. When the car gets to within 18 inches of the floor at which it is to be stopped, the contacts L3D open and insert the resistance R9 in the generator field GF to further decelerate the car.

Fig. 20 provides a chart for the controller M similar to that for the controller L, except for different contacts and different distances, inasmuch as it relates to the rotation of the controller M by the car while it is decelerating from a point 20 feet from the floor to a point 20 inches from the floor at which it is to stop.

CIRCUITS IN CONTROL AND SIGNAL SYSTEM—FIGS. 21 AND 22

As illustrated in the control system, the hoisting motor 14 is provided with an armature 14A which is mechanically connected to the shaft 11a for driving the hoisting sheave 11. The motor includes the usual shunt type main field winding 14F which is connected for energization across the supply conductors L+1 and L-1. The armature 14A is connected for energization by a loop circuit 306 to a generator G provided with an armature GA. The brake 15 is provided with a winding 15a which is energized on energization of the motor 14. The generator G is connected for operation by a constant speed-alternating current motor MG.

In order to control the direction and magnitude of the voltage generated by the generator, it is provided with a separately excited main field winding GF. A plurality of resistor sections R2 to R11, inclusive, are included in the circuit of the field winding GF to provide speed control for the motor 14. The connection of the resistor sections in the generator field winding GF is controlled by the motor controller M and the leveling controller L, partly by contacts on the controllers and partly by speed relays controlled by the controller M. The generator is also provided with a suitable means, such as a series field winding GS, for correcting the speed regulation of the motor.

An up-direction switch U and a down-direction switch D are provided for connecting the generator field winding GF to the conductors L+1 and L-1 in accordance with the direction it is desired to operate the car. A car-running relay 6 is so connected as to be energized, when either of the direction switches is energized, for the purpose of conditioning certain controlling circuits for operation. The common circuit of the switches U and D and the running relay 6 includes the usual safety devices indicated at 17.

An up-direction preference relay W and a down-direction preference relay X are provided for causing the car to continue in the direction in which it is started until it arrives at the terminal toward which it is moving and for connecting certain other circuits in accordance with the direction of operation. The operating windings of these relays are controlled by a bottom limit switch DLS and by a high call reversal relay 38R. The limit switch DLS reverses the direction preference relays when the car arrives at the bottom terminal and the relay 38R reverses them.

when the car arrives at the top terminal or when the car is moving upwardly and no call exists above it.

Normally the direction preference relays are reversed only at the terminals or while the car is moving upwardly between terminals and no call exists above it. However, car-reversing buttons UPB and DPB are connected in the circuits of the direct preference relays so that the attendant may reverse the car at any time by operating the reversing buttons if he finds it desirable to do so. The direction preference relays are connected to control the direction of the car by the inclusion of their direction contacts in the circuits of the up direction switch U and the down direction switch D to prepare for operation of the direction switch corresponding to the direction the car is to move.

A starting relay 80 connected to be operated by the starting button CS on the car is provided for initiating the closing of the door and for completing the energization of the direction switch which has been prepared for operation by the direction preference relays.

25 A plurality of speed relays GR4, GR6 and GR8 are provided for short circuiting the sections R2, R3 and R4 of the resistor in circuit with the generator field winding GF to control the speed of the hoisting motor 14. The motor controller M 30 controls the energization of the speed relay GR4 and also prepares for operation of the relays GR6 and GR8 by contacts disposed on the controller drum. When the relay GR4 operates it shorts sufficient resistance to give enough speed for a 35 one floor run. When the relay GR6 operates, it shorts sufficient resistance to give enough speed for a two floor run. When the relay GR8 operates, it shorts sufficient resistance to bring the car up to full high speed.

40 A time delay control means for limiting the acceleration of the hoisting motor comprises a pair of time relays GR6T and GR8T for controlling the energizing circuits of the relays GR6 and GR8 to prevent their operation until after the 45 expiration of predetermined periods of time subsequent to operation of the relay GR4. A resistor R12 is disposed in parallel with the relay GR6T and a resistor R13 in parallel with the relay GR8T to give them the required delay on being deenergized. Each relay may be given a delay of approximately $\frac{1}{2}$ second.

The coils for the up-stopping and leveling inductor relay UF and the down-stopping and leveling inductor relay DF are connected for operation by the speed relay GR4 and are provided not only for deenergizing the direction switches to stop the car and apply the brakes, but also for causing the leveling controller L, after the controller M has decelerated the car in coarse steps, to start decelerating it in fine steps when it is twenty inches from the floor. The inductor relays are also used for releveling the car while it is standing at a floor if it moves above or below the floor under the influence of loading or cable stretch.

An auxiliary up-stopping relay UE, and an auxiliary down-stopping relay DE and a clutch magnet control relay H, disposed to be controlled by the up and the down inductor relays, are provided for controlling the deenergization of the up-direction switch U and the down-direction switch D and also the transfer brake magnet TM.

An auxiliary leveling relay 65 controlled by the speed relay GR4 is provided for controlling the

time delay relay GR6T and for assisting in controlling the inductor relays UF and DF.

A control conditioning relay 32T is disposed in parallel with the brake coil 15a, and the contacts operated by it are used for conditioning certain circuits of the control system when the brake is operated. The relay 32T is a time relay which is slow on dropping out when deenergized, as indicated by the dashpot associated with the coil. It may be given a delay of from one to two seconds, depending upon the conditions under which the car operates.

An energization stop and pre-energization relay 7 is associated with the direction switches U and D for closing the circuit from the generator to the hoisting motor after the generator has been energized to start the hoisting motor and for inserting a resistor RI in circuit with the armature of the hoisting motor to deenergize it quickly when the circuit to the hoisting motor is opened.

An open-door safety relay 40 controlled by a safety contact on the doors is provided for preventing operation of the car when any door is open.

A door relay 45 operated by the starting relay 80 is provided for closing the doors and holding them closed while the car is moving.

An auxiliary door relay 22 operated by the controller L is provided for causing the doors to start opening when the car approaches to within say, nine inches of the floor at which it is to stop.

A leveling relay 43T, having a dropout time delay of one to two seconds, is provided for controlling the brake transfer magnet TM during releveling operations of the car when it becomes unlevel with a floor during a stop thereat by reason of cable stretch or loading. The relay 43T differentiates between a leveling operation when the car overshoots or underruns the floor and a releveling operation when the car becomes unlevel with a floor while in a stopped condition thereat. In the leveling operation, the controller L is in operation and gives a rapid movement into the floor level. In a releveling operation, the relay 43T keeps the brake on the controller L and the releveling is slow so as to prevent "pumping."

A torque-relay T controlled by the pawl magnets UPP and DNP is provided for decreasing the torque of the advance motor when the car picks up a stop-call signal.

Associated with each of the hall-stop buttons is a call registering or storing relay, by means of which the momentary pressing of the button will set up or register a stop call which will remain registered until it is answered by the car. These relays are designated as 1UR, 2UR, etc., for the up buttons 1UB, 2UB, etc., and as 1IDR, 10DR, etc., for the down buttons 1IDB, 10DB, etc. In order to conserve space on the drawings, up buttons have been shown for only the 1st, 2nd, 7th, 8th, 9th and 10th floors, and down buttons for only the 11th, 10th, 9th, 8th, 7th and 2nd floors. A call-cancelling coil 2DNR is associated with the call-registering relay 2DR for the 2nd floor hall button for the down direction so that the car may energize the coil 2DNR and thereby cancel the call when it answers it. Each call registering relay has a similar cancelling coil.

A hall-call stopping relay 438 is provided for energizing the up-pawl magnet or the down-pawl magnet whenever the car approaches a registered stop call on a hall button. The stopping relay 438 is controlled through a circuit set up by contacts on the call-registering relays and contacts

on the floor selector. A holding coil 438H is disposed on the stopping relay 438 and so wound thereon so as to add its holding energy to the energizing of the coil 438. The purpose of the holding coil 438H is to hold the relay 438 energized until the doors are closed, preparatory to the next start. If it were not for the holding coil, the relay 438 would drop out when the hall call is canceled.

The up-pawl magnet coil UPP is disposed on the up carriage UC for operating the armature 114 on the carriage, and it is controlled through the circuits of the car-call buttons and by the hall-call stopping relay 438 so that as the car approaches a stop registered on either the car buttons or the hall buttons, the magnet UPP will be energized to stop the car at the floor of the call. The down-pawl magnet DPP is disposed on the down carriage DC and is responsive to the same controls as the magnet UPP on the up carriage UC, except that contacts L10D and L10U on the leveling controller L prevent the up-pawl magnet from being energized when the car is going down, and prevent the down magnet DNP from being energized when the car is going up.

Each of the car buttons 2C, 3C, etc., is provided with a holding coil, such as CC, by means of which the momentary pressing of the button will set up or register a stop-call for the corresponding floor which will remain registered until the car stops at that floor. The car-call retaining coils are controlled by the direction preference relays W and X so that only one set of car buttons is necessary and all of the calls thereon are released when the car changes its direction of operation.

The no-hall-call-above relay 78 is provided for determining when there is no hall-call registered for a floor above the car. The relay is controlled by a circuit connected between the conductors L+3 and L-3, which includes in series contacts of the various hall-call registering relays and floor selector contacts operated in accordance with the position of the car. The relay is energized when no hall call is registered above the car.

The no-car-call-above relay 38R is provided for determining when there is no stop call registered on the car buttons for a floor above the car. It is controlled by a circuit through the car buttons 50 and contacts on the floor selector, so that it will be energized as long as an unanswered call above the car while it is going up remains unanswered. The relay 38R is also controlled by contacts of the no-hall-call-above relay 78 and contacts of the 55 hall-call-stopping relay 438, so that it cannot be deenergized as long as a hall call above the car remains unanswered. The no-car-call-above relay 38R is also used as a high-call reversal relay, because its contacts 38R1 are disposed in one of the circuits for the up-direction preference relay W, and once that relay is energized, it will remain energized until the car reaches the upper terminal or until the relay 38R is deenergized because there is no call, either car or hall, above 60 the car.

The advance motor AM is provided with an armature AMA, an up-direction field winding AMFU and a down-direction field winding AMFD. The field windings are controlled by the direction preference relays W and X, and a resistor R14 is disposed in circuit with the field windings so that the torque of the motor can be reduced when it has moved the controller M to its full "on" position or when either carriage pawl is energized for a stop. Any electric motor capable of

23

generating a torque under stalling conditions may be used.

However, the torque of the advance motor AM should be relatively less than the torque of the synchronous motor SM so that the motor SM may overcome the motor AM and rotate it in its other direction when the controllers are to be rotated from their "on" positions to their "off" positions by the car during deceleration of the car.

The clutch magnet coil CM for releasing the clutch 26 is controlled by the clutch magnet relay H which, in turn, is operated by the inductor relays when the car reaches such a distance, say 20 inches, from the floor in making a stop that the motor controller M should be disconnected from operation by the differential K2.

The brake transfer magnet TM is connected with the controller brakes 27 and 29 and is controlled by the clutch magnet relay H and the leveling relay 43T for releasing the brake 29 and applying the brake 27 when the controller M is to be operated by the differential K2.

The circuit of the clutch magnet CM includes the contacts ER1 of the express relay. The circuit of the pawl magnets DNP and UPP includes the contacts ER2 of the express relay and the contacts ERX1 of the express time delay relay. These contacts are operative only when the system is connected for an express car installation. Otherwise, they have no effect on the system and may be ignored.

ASSUMED OPERATION OF CAR FROM LOWER TERMINAL TO A STOP AT THE SEVENTH FLOOR.

It will be assumed that the car is standing at the lower terminal with its doors open, and that it is ready for an up trip. Under these conditions, the up inductor relay coil UF and the down inductor coil DF are energized by the circuit L+1b, 45-1, GR4-2, UF, DF, L-1 for leveling purposes. The time delay relay GR6T is energized by the circuit L+1, 65-1, GR6T, L-1a, and the time delay relay GR8T is energized by the circuit L+1, GR6-2, GR8T, L-1a.

The no-hall-call-above relay 78 is energized by the circuit L+3, 11DR2, 10UR2, 10DR2, etc., 1S2, 78, L-3. The transfer brake magnet coil TM is energized by the circuit L+1, 80-5, 43T1, TM, L-1a, thus holding the brake 27 on the controller L. The up direction preference relay W is energized by the circuit L+1, DPB, 32T2, X3, W, L-1a. The down pawl magnet is energized by the circuit L+3, ERX1, 80-6, DNP2, DNP, L-3.

It will be assumed now that a waiting up passenger at the 7th floor presses the up button L1UB at that floor to cause the car to stop thereat. The pressing of the button energizes the up-call registering relay 7UR by the circuit L+2, 7UB, 7UR, L-2 and thereby registers a stop call at the 7th floor. The energized relay 7UR closes its self-holding contacts 7UR1 and opens its contacts 7UR2. The opening of the contacts 7UR2 deenergizes the no-hall-call-above relay 78 because there is an up call above the car.

It will be assumed now that the attendant in the car presses the start button CS to cause the car to close its doors and start on an up trip during which it will slow down and stop at the 7th floor in answer to the up call registered thereat.

The pressing of the button CS energizes the starting relay 80 by the circuit L+1, CS, 80, L-1a to start the car. The energized relay 80

24

closes its contacts 80-1, 80-2, 80-3, 80-4, and opens its contacts 80-5 and 80-6.

The opening of the contacts 80-5 deenergizes the brake transfer magnet TM so that it releases the brake 27 from controller L and the spring 32 applies the brake 29 to the shaft of the controller M. The opening of the contacts 80-6 opens the holding circuits for the pawl magnets DNP and UPP to prepare them for the up trip.

The closing of the contacts 80-1 energizes the up direction switch U and the running relay 6 by the circuit L+1, 17, W1, 80-1, DE1, U, 6, L-1a. The relay 6 closes its contacts to prepare various circuits for operation. The relay U closes its contacts U1 to prepare the brake circuit for operation, U4 to prepare a holding circuit for itself, U5 to complete a running circuit for the relay W, and U2 and U3 for energizing the generator G for up direction operation by the circuit L+1, U2, GF, U3, R2 to R4, L-1. The generator G is now pre-energized and ready for energizing the motor 14, but does not affect it as yet because the contacts 7-2 are open in the loop circuit 17.

The closing of the contacts 80-3 energizes the door operating relay 45 to close the doors (not shown) by the circuit L+1, 45, 80-3, L-1a. The relay 45 starts the door closing motor (not shown), closes its contacts 45-2, and opens its contacts 45-1. The closed contacts 45-2 prepare the circuits for the pawl relays DNP and UPP. The opening of the contacts 45-1 deenergizes the inductor relays UF and DF, returning them to normal.

The closing of the contacts 80-4 energizes the advance motor AM by the circuit L+1b, 80-4, L12, T1, M13U, M13D, W2, AMFU, AMA, L-1.

The energized motor AM starts rotation of the controller L to its "on" position, by operation of the shaft 168 (Figs. 11 to 18), shaft 166, gears 231 and 232, shaft 233, gear 228, shaft 236, differential K2, gears 248 and 259, shaft 260, gears 263 and 264, shaft 265, gears 266 and 267, shaft 268 and 28, and the controller drum shaft 188.

The controller L will be rotated to its full "on" position by the end of one-fourth second and will sequentially close its contacts L1U, L2U, L9U, L10U, L11U and open its contacts L12. The closing of the contacts L1U, L2U, and L3U shorts the resistors R11, R10, and R9 in the generator field, but this has no effect on the speed of the hoisting motor because it has not yet been connected to the generator.

The closing of the contacts L9U prepares a circuit for the auxiliary door relay 22. The closed contacts L10U prepare a circuit for the pawl magnet UPP. The closing of the contacts L11U energizes the brake transfer magnet TM by the circuit L+1, L11U, W5, H4, TM, L-1a to release the brake 29 from the shaft of the controller M and apply the brake 27 to the controller L so that further operation of the differential K2 will not affect the controller L. The opening of the contacts L12 deenergizes the advance motor AM and stops it. The controller L is stopped in its full "on" position not only by the brake 27 and the motor AM but also by the lug 198 engaging the stop shoulder 199a.

Simultaneously with the operation of the controller L, the advance motor advanced the up direction carriage UC to a position equal to a lead of 20 inches on the car.

This operation was effected by the advance motor operating the gear 228 as before described, which, in turn, operated the ring gear 226 on the differential K1 and, because the synchronous

motor SM had not yet started, thereby operated the differential gear 216, the shaft 211, the gears 219 and 220, the shaft 159, and shaft 157, thus rotating the sprocket wheel 136 to move the up carriage UC upwardly through the operation of the chain drive 23. The up movement of the carriage UC by the chain drive causes the down carriage DC to move downwardly.

At the end of one-fourth second, the carriage UC has a lead of 20 inches on the car and is stopped, the motor AM is stopped, and the controller L has reached its full "on" position and is stopped against its up limit lug 199a.

After the expiration of approximately 1 second, the doors reach their closed positions and thus close their safety contacts 31a to energize the door safety relay 40 by the circuit L+1, 31a, 40, L-1a. The energized relay 40 closes its contacts 40-1, 40-2, 40-3, 40-4, 40-5, and opens its contacts 40-6. The closed contacts 40-2 complete a holding circuit for the relay U. The closed contacts 40-1 prepare a circuit for the pre-energizing relay 7. The closed contacts 40-4 energize the time relay 43T to prepare it for action.

The closed contacts 40-5 energize the circuit for the advance motor AM and start it in operation again by the circuit: L+1b, 6-4, 40-5, T1, and M13U and M13D, W2, AMFU, AMA, L-1. The energized motor AM now restarts the chain drive 23 by the gearing previously described for moving the up carriage UC farther into its lead on the car and also starts rotating the controller M toward its "on" position by the shaft 236, differential K2, differential gear 240, shaft 241, gears 250, 251, and 254, shaft 30, the controller drum shaft 173. The controller M now starts to close its contacts M1U, M2U, M3U, M4U, M5U, M6U, M7U, M8U and open its contacts M13U. As the contacts M1U to M4U close, they short circuit resistors R5, R6, and R7, but this does not affect the hoisting motor because that motor has not yet been connected to the generator.

The controller M rotates fairly rapidly and closes its contacts M5U before the hoisting motor gets started. As the contacts M5U close, they energize the speed relay GR4 by the circuit L+1b, M5U, GR4, 6-2, 40-3, L-1. The energized relay GR4 closes its contacts GR4-1, GR4-3, and opens its contacts GR4-2. The closed contacts GR4-1 short out the resistor sections R4 to R11 in the field winding GR to enable the car to accelerate rapidly when it starts. The open contacts GR4-2 prevent the inductor relays UF and DF from being energized while the car is operating above the speed determined by the speed relay GR4. The closing of the contacts GR4-3 energizes the auxiliary leveling relay 65 by the circuit L+1, GR4-3, 65, 6-5, L-1a.

The energized leveling relay 65 opens its contacts 65-1 and closes its contacts 65-2 and 65-3. The opened contacts 65-1 deenergize the time relay GR6T which will close its contacts GR6T-1 after one-half second to time-control the acceleration of the hoisting motor. The closed contacts 65-2 prepare one circuit for the inductor relay DF and UF. The closed contacts 65-3 provide a self-holding circuit for relay 65.

When the door safety relay 40 energized the advance motor AM, its closed contacts 40-3 energized the auxiliary door relay 22 by the circuit L+1b, L9U, 22, 6-2, 40-3, L-1. The energized relay 22 closes its contacts 22-1 and 22-2. The contacts 22-2 provide a holding circuit for the door operating relay 45 so that the starting but-

ton CS may now be released by the car attendant. The closed contacts 22-1 energize the pre-energization relay 7 by the circuit L+1, 17, 7, 6-1, 40-1, 22-1, L-1a.

The energized relay 7 closes its contacts 7-2 and 7-3 and opens its contact 7-1. The opening of the contacts 7-1 opens the demagnetizing circuit for the armature 14a and the closing of the contacts 7-2 completes the loop circuit 306 from the generator G to the motor 14 so that the hoisting motor is now energized to start the car upwardly. The closing of the contacts 7-3 energizes the brake coil 15a to release the brake 15 and the car now starts to move upwardly, about 1 1/4 seconds after the pushing of the start button. By this time the controller M has rotated about 75° and the carriage UC has a lead on the car of approximately 9 feet.

When the contacts 7-3 closed to energize the brake coil, they also energized the control conditioning relay 32T by the circuit L+1, 32T, 7-3, U1, L-1. The energized relay 32T closes its contacts 32T1, 32T3 and 32T4 and opens its contacts 32T2. The closed contacts 32T1 provide a holding circuit for the pre-energization relay 7 under certain conditions. The opened contacts 32T2 maintain open one circuit to the preference relay W while the car is running. The closed contacts 32T3 prepare a holding circuit for the pawl magnets DNP and UPP. The closed contacts 32T4 prepare a circuit for the holding coil 438H on the stopping relay 438.

As the controller M continues to rotate, it closes its contacts M6U thus preparing a circuit for the speed relay GR6. The timing relay GR6T for the speed relay GR6. The timing relay GR6T now times out and closes its contacts GR6T-1 thus energizing the speed relay GR6 by the circuit L+1b, M6U, GR6T1, 6-2, 40-3, L-1. The energized relay GR6 closes its contacts GR6-1 and opens its contacts GR6-2. The closed contacts GR6-1 short circuit the resistors R3 to R11 in the field winding GF to increase the speed of the car.

The opened contacts GR6-2 deenergize the timing relay GR6T.

Meanwhile the controller M continues to rotate and closes its contacts M7U thereby preparing a circuit for the speed relay GR8. After the relay GR8T has been deenergized for 1/2 second, it closes its contacts GR8T1 thereby energizing the speed relay GR8 by the circuit L+1b, M7U, GR8, GR8T1, 6-2, 40-3, L-1. The energized relay GR8 closes its contacts GR8-1 thereby short-circuiting the resistors R2 to R11 in the field winding GF of the generator and the car now accelerates to its normal high speed of 800 ft. per minute.

While this accelerating action has been taking place, the controller M has been rotating toward its full "on" position and at approximately 2 3/4 seconds after operation of the starting button, it opens its contact M13U and its stop lug 182 stops it against its limit lug 183. The opening of the contacts M13U inserts the resistor R14 in the circuit of the advance motor AM to reduce the torque of that motor inasmuch as it is being stalled by the stopping of the controller M.

By the time the controller M reaches its full "on" position, the car has moved about two feet away from the floor and the up carriage has been moved to a position in advance of the car equal to about 20 feet ahead of the car, its normal leading position. This leading position of the up carriage has been attained rather rapidly because when the car started, it caused the synchronous

motor SM to add its movement to the differential K1 at that time being operated by the advance motor AM thereby increasing the acceleration of the up carriage to its 20 feet lead ahead of the car.

As the controller M stops against its limit lug and stalls the advance motor, the continued operation of the synchronous motor SM by the car takes over the operation of the up carriage and causes it to keep moving with its lead of approximately 20 feet on the car until the carriage arrives at a floor for which a stop call is registered.

As the car continues upwardly, the roller 145 on the up carriage UC operates the blocks of P contacts on the floor selector to light the position lamps (not shown) in the position indicator, and at the same time, the rollers 150 and 151 on the down carriage sequentially operate the blocks of S contacts for the floors to pick up stop calls, etc. It should be noted here that the up contacts for any floor may be disposed to be operated by either the up or the down carriage and that likewise the down contacts for any floor may be disposed to be operated by either the up or the down carriage, inasmuch as the carriages are always positioned for the same floor.

Consequently, when the car approaches the 5th floor and the down carriage DC, being approximately 20 feet ahead of the car, reaches its seventh floor position, its rollers 150 and 151 close the contacts 7S4 and thereby complete the stop circuit set up by the up-call-registering relay 7UR for the stop call at the 7th floor and energize the stopping relay 438 by the circuit L+2, 7UR, 7S4, W7, 438, L-2.

The energized relay 438 closes its contacts 438-2, 438-3 and 438-4 and opens its contacts 438-1. The closed contacts 438-4 energize the holding coil 438H by the circuit L+2, 32T4, W8, 438-4, 438H, L-2. The contacts 438-1 open in one circuit to the relay X to condition that relay in connection with high-call-reversal operation. The closed contacts 438-2 energize the no car call above relay 38R by the circuit L+3, 438-2, 11S1, 38R, 6-7, L-3. The energized relay 38R closes its holding contacts 38R3, closes its contacts 38R1 in one circuit of the direction relay W and opens its contacts 38R5 in one circuit leading to the up pawl UPP. The opening of the contacts 38R4 opens the reversing circuit associated with the down pawl DNP.

The closed contacts 438-3 energize the up-pawl magnet UPP by the circuit L+3, 438-3, 45-2, L10U, UPP, L-3, to cause the car to be stopped at the 7th floor to answer the up-stop call registered at that floor.

The energized up-pawl magnet UPP closes its contacts UPP1, UPP2 and UPP3 mounted on the up carriage UC. The closing of the contacts UPP1 energizes the torque relay T by the circuit L+1b, UPP1, T, L-1 to open its contacts T1 to maintain the resistor P14 in series with the advance motor AM.

The closed contact UPP2 closes one part of the circuit to the down-pawl magnet DNP for a reversing operation should there be no calls above the car. The closing of the contacts UPP3 provides a holding circuit for the up-pawl magnet UPP which will be maintained until the call is answered at the 7th floor.

The energization of the up-pawl magnet UPP also operates its armature 114 to move its stop roller 121 and its contact roller 143 outwardly. The outward movement of the stop roller 121 causes it to engage the up stop lug 7UN and thereby lock the up carriage UC against further

movement until the up stop call at the 7th floor is answered.

The outward movement of the roller 143 on the carriage closes the contacts 7U1 and 7U2 for the 5th floor. The closing of the contacts 7U1 lights the up floor lantern 7LMU at the 7th floor to indicate to waiting passengers thereat that the car will stop for them by the circuit L+2, 7LMU, 7U1, 38R6, L-2. The closing of the contacts 10 7U2 energize the cancellation coil 7UNR to de-energize the call-storing relay 7UR and thus restore it to its normal condition. The deenergized relay 7UR recloses its contacts 7UR2 and thereby again energizes the no-call-above relay 78.

15 Inasmuch as the up carriage UC is now stopped in its 7th floor position and cannot move, the chain drive 23 is stopped thereby locking the gear wheels 220, 219 and 216 against further rotation by the differential K1. Inasmuch as the 20 differential gear 216 cannot move, the continued rotation of the gear wheel 213 by the operation of the synchronous motor SM will cause the gear wheels 214 and 215 to rotate the ring gear 227 and thereby operate the gears 228, 235, 232, and 231 25 in reverse direction and thus cause the motor AM to rotate backwardly. At the same time, the rotation of the gear wheel 228 by the synchronous motor SM through the differential K1, rotates the gear 237 of the differential K2 in reverse direction to its prior operation and thereby operates the gear wheels 240, 250, 251, and 254 to reverse the operation of the controller M so that it will now rotate it from its full "on" position to its "off" or neutral position while the car is decelerating to the point where the inductor relay transfers the decelerating action to the landing controller L.

The first few degrees of movement of the controller M from its "on" position (Fig. 20) closes its contacts M13U and opens its contacts M7U. The closing of the contacts M13U has no effect. The opening of the contacts M7U deenergizes the speed relay GR6 which opens its contacts GR81 and inserts the resistor section R2 45 in the field winding GF to decrease the speed of the hoisting motor.

As the car decelerates to a position approximately 11 feet from the 7th floor, it rotates the controller M to open its contacts M6U thereby deenergizing the speed relay GR6 which opens its contacts GR61 thus inserting the resistor R3 in series with the generator field winding GF to further decrease the speed of the car. The deenergized relay GR6 also closes its back contacts 55 GR6-2 to restore the time delay relay GR8T.

As the car decelerates from its 11-foot position to within 6 feet of the 7th floor, it rotates the controller M to open its contacts M5U thus deenergizing the relay GR4 to open its contacts GR41 and insert the resistor R4 in the circuit of the generator field winding to further decrease the speed of the car.

The deenergization of the relay GR4 also closes its contacts GR2 and thereby energizes the inductor relays UF and DF by the circuit L+1b, 65-2, GR4-2, UF, DF, L-1, so that they are ready for operation when the car arrives at the inductor plate IP for the 7th floor.

As the car decelerates to within 5 1/2 feet of the 7th floor, it rotates the controller M to open its contacts M4U thereby inserting the resistor R5 in the generator field winding circuit to further reduce the speed of the car.

As the car decelerates to within 3 1/2 feet of the 7th floor, it rotates the controller M to open its

contacts M3U thereby inserting the resistor R6 in the generator field winding to further reduce the speed of the car.

As the car decelerates to within 3 feet of the 7th floor, it rotates the controller M to open its contacts M2U thereby inserting the resistor R7 in the generator field winding to still further reduce the speed of the car.

As the car decelerates to within 2 feet of the 7th floor, it rotates the controller M to open its contacts M1U thereby inserting the resistor R8 in the generator field winding to further decelerate the car until, as it reaches a point 20 inches from the 7th floor, its speed has been reduced to approximately 100 feet per minute.

As the car arrives at a point 20 inches from the 7th floor, its inductor relay UF is brought opposite the inductor plate IP for the 7th floor. The influence of the plate causes the up contacts UF1 to close and thus energize the auxiliary up stop relay UE and the clutch magnet control relay H by the circuit L+1, UF1, UE, H, L-1a.

The energized relay H closes its contacts H1, H2 and H3 and opens its contacts H4. The closed contacts H1 prepare an additional circuit for the pre-energizing relay 1 to keep it from dropping when the auxiliary door relay opens. The closed contacts H2 prepare a leveling circuit for the advance motor AM. The closed contacts H3 energize the clutch magnet CM by the circuit L+1b, H3, CM, L-1. The energized clutch magnet opens the clutch 26 and in so doing causes the centering pin 34 to enter the centering hole 304 on the centering plate on the controller M and thereby center the controller in its correct position for the next operation. The opening of the contacts H4 deenergizes the brake magnet TM whereupon the spring 32 applies the brake 29 to the shaft 30 of the controller M and releases the brake 27 from the shaft of the leveling controller L, leaving it free to be operated by the differential K2.

As the car continues to move upwardly toward the 7th floor, the operation of the differential K2 by the synchronous motor SM, rotates the controller L from its full "on" position for the up direction toward its "off" position.

As the car moves to within 19 inches of the 7th floor, it rotates the controller L to close its contacts L12 and open its contacts L11U. The closing of the contacts L12 provides an additional circuit for the advance motor AM so that it can remain energized when the doors open. The opening of the contacts L11U has no effect because the brake transfer magnet was deenergized by the opening of contacts H4.

As the car moves to within 18 inches of the 7th floor, it rotates the controller L to open its contacts L10U and L3U. The contacts L10U have no effect in this operation as they are for express operation. The opening of the contacts L3U inserts the resistor section R9 in the circuit of the generator field winding to further reduce the speed of the car.

As the car decelerates to within 9 inches of the 7th floor, it rotates the controller L to open its contacts L9U thereby deenergizing the auxiliary door relay 22 which opens its contacts 22-2 and thereby deenergizes the door operating relay 45 which, in turn, starts the doors to open.

As the car decelerates to within 7 inches of the 7th floor, it rotates the controller L to open its contacts L2U thereby inserting the resistor R10 in the generator field winding to still further reduce the speed of the car.

As the car arrives at approximately 5 inches from the 7th floor, the doors start to open and thus open their contacts 31 and thereby deenergize the door safety relay 40 which, in turn, opens its contacts 40-4 and thereby deenergizes the leveling relay 43T which will, after a delay of one or two seconds, time out and reclose its back contacts 43T1 to permit operation of the brake transfer magnet TM so that the inductor relay may operate to level the car back to the floor in case it moves away from the floor by reason of cable stretch or other conditions.

As the car decelerates to within 1 inch of the 7th floor, it rotates the controller L to open its contacts L1U thus inserting the resistor R11 in the field winding to reduce the speed of the car down to a landing speed of approximately 10 feet per minute.

As the car decelerates to within $\frac{5}{8}$ of an inch of the floor level at the 7th floor, the up contacts UF1 on the inductor relay UF pass beyond the upper end of the inductor plate IP which causes them to open and deenergize the relays H and UE.

The deenergized relay H opens its contacts H3 and thereby deenergizes the clutch magnet CM. However, the brake 29 is on the shaft 30 and the motor AM will be deenergized by the relay 6 and hence the controller M will not be actuated.

The deenergized relay UE opens its contacts UE1 and thereby deenergizes the up direction switch U and the running relay 6. The deenergized switch U opens its contacts U2 and U3 in the generator field winding to deenergize the motor, and opens its contacts U1 to deenergize the brake coil 15a and the control conditioning relay 32T.

The deenergization of the brake coil causes the brake 15 to be applied to the hoisting motor and thereby stop the car level with the 7th floor, as it will slide only $\frac{5}{8}$ of an inch while the brake is setting.

The deenergized running relay 6 opens its contacts 6-4 and thereby deenergizes the advance motor AM and also opens its contacts 6-5 to deenergize the auxiliary leveling relay 65 which, in turn, closes its contact 65-1 to restore the time relay GR6T.

The deenergized relay 32T now opens its contacts 32T1 after a delay of one or two seconds and thereby deenergizes the preenergizing relay 7 which, in turn, closes its back contact 7-1 to restore the resistor R1 in circuit with the armature 14A and opens its contact 7-2 in the loop circuit 306 between the generator and the motor so that the generator will be preenergized ready for the next operation.

The deenergized relay 43T now closes its back contacts 43T1 after its usual time delay and thereby reenergizes the brake transfer relay TM which applies the brake 27 to the controller L and releases the brake 29 from the controller M, thereby completing the operation of moving the car from the lower terminal to the 7th floor and stopping it thereat.

65 CAR LEAVES 7TH FLOOR, STOPS AT 10TH FLOOR IN RESPONSE TO OPERATION OF PUSH BUTTON IN CAR AND REVERSES BECAUSE NO CALL ABOVE

It will be assumed now that the waiting passenger at the 7th floor enters the car and asks to be let off at the 10th floor and that the car attendant temporarily presses the car stop button 10C to register a call to stop the car at the 10th floor when it arrives thereat so that the passenger can get off at that floor.

75 The pressing of the button 10C causes it to be

held in by its holding coil 10CC and to complete a supplementary circuit L+3, 10C, 10S1, 11S3, 11S1, 38R, 38R3, L-3 for the no car call above relay 38R, to prevent reversal of the car before the call on button 10C is answered.

It will be assumed now that the car attendant presses the start button CS to cause the car to resume its up trip. The closed button CS energizes the starting relay 80 which in turn energizes the door closing relay 45, the up direction switch U, the car running relay 6 and the advance motor AM and deenergizes the brake transfer relay TM, as described in starting from the 1st floor.

It may be noted here that whenever the relay 6 is energized in running the car, it closes its contacts 6-7 in one branch of the circuit for the no car call above relay 38R so that any operated car button for a floor above the car will complete a circuit through the relay 38R and energize it to prevent reversal of that car until that car button stop call is answered.

The energized starting relay 80 also opens its contacts 80-6 and thereby deenergizes the up pawl magnet UPP which releases its pawl arm 110 so that the spring 118 on the carriage returns the pawl arm to its normal inner position. The return movement of the pawl arm carries the roller 121 away from the up stop lug 10UN, leaving the carriage UC free to move ahead of the car. The return movement of the pawl arm also carries the roller 143 away from the contacts 7U1, causing them to open and thereby extinguish the up hall lantern 7LMU at the 7th floor.

The advance motor AM starts the chain drive 23 to keep the carriage UC moving ahead of the car and also rotates the leveling controller L toward its "on" position while the door operating relay 45 starts the doors to close. At the end of one-fourth second, the chain drive has advanced the carriage to a lead of 20 inches and the leveling controller L has rotated to its full "on" position and stopped against its limit lug 199a. As the controller L completes its movement, it opens its contacts L12 to stop the advance motor AM, and thus the carriage, and closes its contacts L11U to energize the brake transfer magnet TM to apply the brake 27 to the controller L and release the brake 29 on the controller M, as in the former operation.

At the end of approximately one second, the doors reach their completely closed position and thereby energize the door safety relay 40. The relay 40 opens its contacts 40-6 thereby deenergizing the holding coil 438H to cause the stopping relay 438 to return to its normal condition. The relay 438 now opens its contacts 438-2 but the relay 38R remains energized by the retaining circuit through the button 10C.

The energized relay 40 also energizes the auxiliary door relay 22, the leveling relay 43T and the advance motor AM. The relay 22 energizes the preenergization relay 7 and the advance motor simultaneously starts rotating the controller M toward its "on" position and operates the chain drive 23 to restart the carriage UC toward its lead on the car. As the controller M rotates, it closes its contacts M1U, M2U, M3U, M4U and M5U, as previously described, to remove the resistor sections R8, R7, R6, R5 and R4 from the generator field winding circuit, all as in the previous up operation.

The preenergization relay 7 operates its contacts to connect the hoisting motor to the generator and energize the brake coil to release the

brake to start the car upwardly. At the end of one and three-fourths seconds the brake has released and the hoisting motor now causes the car to leave the 7th floor.

The car, the carriage and the controller now operate as described in the movement from the bottom landing, and as the car arrives at the 8th floor, the carriage, having a lead of 20 feet on the car, picks up the stop call registered on the call 10 button for the 10th floor, by closing the contacts 10S5 on the floor selector and thereby energizes the pawl magnet UPP by the circuit L+3, 10C, 10S5, 45-2, L10U, UPP, L-3.

Also the roller 145 on the carriage opens the contacts 10S1 and 10S3 to prevent certain sneak circuits and to deenergize the no call above relay 38R, so that the car will stop and reverse its operation at the 10th floor inasmuch as no purpose will be served by running the car upwardly any further. This reversal will be effected when the up direction switch U opens its contacts U5 at the 10th floor stop, because the control conditioning relay 32T and the deenergized relay 38R have opened their contacts 32T2 and 38R1 in the 25 branch circuits of the up direction preference relay W.

The energized pawl magnet closes its contacts UPP1, UPP2 and UPP3 to effect the results previously described, and also releases its pawl arm 110 which is thereupon moved outwardly by its spring 118. The outward movement of the pawl arm moves its roller 121 against the stop lug 10UN for the 10th floor and its roller 143 outwardly against the contacts 10U1 to close them.

Ordinarily, the closing of the contacts 10U1 by the roller 143 would light the up floor lantern 10LMU at the 10th floor, but in this instance, the lantern 10LMU fails to light because the contacts 38R6 of the reverse relay 38R are open. There being no call above the car, it is going to reverse at the 10th floor and no up floor lantern is needed.

However, inasmuch as the car is going to reverse and start down, the down floor lantern 10LMD at the 10th floor is lighted because the down pawl magnet DNP is energized by the circuit L+3, 38R5, W6, 45-2, UPP2, 38R4, and thereupon causes its roller 149 to close the contacts 10D1 for lighting the down lantern by the circuit L+2, 10LMD, 10D1, L-2.

The engagement of the roller 121 with the lug 10UN locks the carriage in its 10th floor position so that operation of the differential K1 by synchronous motor SM caused by the continued movement of the car will operate the differential K2 and through it rotate the controller M from its "on" position to its "off" position to decelerate the car to its stop at the 10th floor.

Inasmuch as the car in moving from the 7th floor to the 8th floor has not accelerated to its normal speed of 800 feet per minute, the first movement of the controller M in opening its contacts M1U to insert the resistor R2 in the generator field will have no effect on the speed of the car and the speed may even increase some until the controller M opens its contacts M6U because the generator field is still conditioned to provide a car speed of 500 feet per minute as long as the contacts M6U are closed. However, when the controller M reaches the point where its contacts M6U open and insert the resistor R3 in the generator field, then the speed of the car starts to decelerate and as the controller successively closes its contacts M5U, M4U, etc., the car is further decelerated until it arrives at the point where the

inductor relay shifts the deceleration from the controller M to the controller L.

When the car arrives at a position 20 inches from the 10th floor, the inductor relay UF comes opposite the inductor plate IP for the 10th floor, and is operated to open its contacts UF1 and thereby deenergize the auxiliary stop relay UE and clutch magnet control relay H. The relay H throws the controller L into operation by the car as previously described, to decelerate down to stopping speed.

When the car is $\frac{5}{8}$ inch from the floor, the inductor contacts UF1 pass the upper end of the plate IP and are thereby opened, thus deenergizing the auxiliary stop relay UE and the clutch magnet control relay H which operate in their usual manner to deenergize the clutch magnet CM, the advance motor AM, the up direction switch U, the car running relay 6, and the relay 32T to deenergize the motor and apply the brake 15 to stop the car level with the 10th floor, as in stopping at the 7th floor.

The deenergized up direction switch U effects a reversal of the car direction by opening its contacts U5 and thereby deenergizing the up direction preference relay W, because the contacts 38R1 of the deenergized relay 38R and the contacts 32T2 of the timed relay 32T are open in the parallel holding circuits for the relay W. The deenergized relay W closes its back contacts W4, thereby energizing the preference relay X by the circuit L+1, UPB, 39R2, W4, X, DLS, L-1a. This action effects reversal of the car at the 10th floor because there are no calls above it, and, when the attendant next presses the starting button CS, the car will move downwardly to answer any down calls which may be registered. The deenergization of the relay W also opens its contacts W3 and thereby restores the car stop buttons including button 10C to their unoperated condition.

The deenergization of the relay W and the energization of the relay X opens the contacts W2 and closes the contacts X2 in the circuit of the advance motor AM so that that motor will, when next operated, rotate the controllers L and M to their "on" position for the down direction.

The deenergized relay 6 opened its contacts 6-3 and the relay 43T now times out and its contacts 43T1 reclose to energize the brake transfer relay TM to apply the brake 27 to the controller L.

After a delay of one second, the deenergized relay 32T operates to deenergize the up carriage magnet UPP to restore it to normal and to deenergize the pre-energization relay 7 to restore it to normal condition.

It will be assumed now that the passenger who desired to get off at the 10th floor has left the car and that the attendant presses the start button CS to start the car. The pressing of the button CS energizes the relay 80, which in turn energizes the door closing relay 45 and starts the advance motor AM to give the carriage a lead on the car and to rotate the controllers to their "on" position for the down trip. The energized relay 80 in closing its contacts 80-2, also energizes the down direction relay D instead of the up direction switch U, because the up direction preference relay contacts W1 in the circuit of the up switch U are open and the contacts X1 of the down direction preference relay X are closed. The circuit for the down switch D extends L+1, 11, X1, 80-2, UE2, D, L-1a. The energized down switch D closes its contacts D2 and D3, thus

energizing the generator G for down car operation.

It will be assumed now that, after the expiration of one second, the doors close and energize safety relay 40 which in turn energizes the relays 22 and 43T and the advance motor AM, and that the relay 22 energizes the brake coil 15a to lift the brake 15 as described in the previous operation to cause the car to start and move on downwardly where it may answer down calls and finally arrive at the lower terminal where the motion of the car opens the bottom terminal limit switch DLS to deenergize the down direction preference relay X, which thereupon closes its back contacts X3 and thereby energizes the preference relay W by the circuit previously described. The car is now at the lower terminal and is ready for another up trip.

OPERATION OF CAR TO ANSWER A ONE-FLOOR RUN

20 It will be assumed now that the car is standing at the lower terminal and is ready for an up trip, that a large number of passengers enter the car, that a waiting up passenger at the second floor presses the up-hall button 2UB to stop the first up car, and that a waiting passenger at the upper terminal presses the hall button 11DB to register a call thereat.

25 The pressing of the button 2UB energizes the up-call registering relay 2UR to register the call by the circuit L+2, 2UR1, 2UR, L-2.

The energized relay 2UR closes its contacts 2UR1 and opens its contacts 2UR2. The closed contacts 2UR1 complete a holding circuit for the relay and prepare a circuit for energizing the up-pawl magnet of the car as it approaches the second flood so that it will stop thereat. The opening of the contacts 2UR2 deenergizes the no-hall-call-above relay 18 which, in turn, energizes the no car call above relay 38R to prevent reversal of the car, as in the prior operations.

30 The pressing of the button 11DB energizes the call registering relay 11DR by the circuit L+2, 11DB, 11DR, L-2. The energized relay 11DR closes its self-holding contacts 11DR1 for energizing the stopping contacts 11S4 and opens its contacts 11DR2 for operating the no call above relay 18 so that the car will not reverse until it arrives at the upper terminal.

35 50 It will be assumed now that the attendant in the car presses the starting button CS which thereupon energizes the starting relay 80 to start the car. The energized relay 80 energizes the door-closing relay 45, the up-direction switch U, the running relay 6, and the advance motor AM. The doors start closing, the advance motor starts running the carriage UC ahead of the car and rotates the controller L to its full "on" position as in the previous start from the first floor. When 55 the controller gets to its full "on" position, it locks and stops the advance motor AM.

60 After the expiration of one second, the doors close, energizing the door-safety relay 40 which, in turn, energizes the auxiliary door relay 22, the leveling relay 43T and the advance motor AM. The advance motor AM now rotates the controller M toward its "on" position, and resumes the movement of the carriage UC to a lead on the car, while the energized relay 22 energizes the pre-energization relay 7 which, in turn, energizes the brake coil and closes the loop circuit between the generator armature and the hoisting motor armature so that the car starts to move. By this time, the advance motor has rotated the controller drum M to about its 50° position.

By the time the car has moved a few inches, the advance motor AM has rotated the controller M to its 75° position and has given the carriage UC a lead of ten feet on the car. At this point, the up carriage UC reaches its second floor position where its rollers 150 and 151 pick up the stop call at the 2nd floor by closing the floor selector contacts 2S4 to stop the car thereat.

The closing of the contacts 2S4 energizes the stopping relay 438 by the circuit: L+2, 2UR1, 2S4, W1, 438, L-2. The energized relay 438 closes its contacts 438-4, thus energizing the holding relay 438H by the circuit previously described. The energized relay 438 also closes its contacts 438-3, thus energizing the up-pawl magnet UPP by the circuit previously described. The energized magnet UPP closes its contacts UPP1 to energize the torque relay T, closes its contacts UPP2 to prepare one of the reversing circuits, and closes its contacts UPP3 to provide a holding circuit for itself.

The energized magnet UPP also attracts its armature 114 which thereupon moves its pawl arm 110 outwardly. The outward movement of the pawl arm moves its roller 121 into engagement with the stop lug 2UN for the second floor and this stops the up carriage and locks it in its second floor position. The outward movement of the pawl arm also moves the roller 143 outwardly against the contacts 2U1, thus closing them to light the up-hall lantern 2LMU at the second floor by the circuit: L+2, 2LMU, 2U1, 38R8, L-2, to indicate to the up passenger thereat that the car will stop for him. The roller 143 also closes contacts 2U2 to energize cancellation coil 2UNR and thereby cancel the coil at the 2nd floor.

Inasmuch as the up carriage has been stopped in its second floor position and the car is moving upwardly, the continued movement of the car (operating on the differential K1) physically reverses the advance motor AM and starts to rotate the controller M backward to decelerate the car to its stop at the 2nd floor. At the start of this backward rotation, the controller M is in its 75° position, its contacts M5U are in their closed position and the relay GR4 is energized and its contacts GR4-1 closed, thus short-circuiting the resistor sections R5 to R11 in the generator field windings.

Although the car starts to rotate the controller M backwardly to cause deceleration of the car, it will be observed that the car continues to increase its speed during the backward rotation of the controller until the controller reaches its 45° position where it opens its contacts M5U. By this time the speed of the car will have increased to approximately 300 feet per minute. The opening of the contacts M5U deenergizes the speed relay GR4 and it, in turn, opens its contacts GR4-1 and thus inserts the resistor R4 in series with the generator circuit to decrease the speed of the car. By the time the contacts GR4-1 open, the car will have increased its speed to approximately 300 feet per minute and will have approached close to within 5 feet of the 2nd floor.

When the car is approximately 5½ feet from the 2nd floor, the continued rotation of the controller M toward its "off" position opens its contacts M4U and thereby inserts the resistor R5 in the generator field winding to further decelerate the car. As the car comes within 3½ feet of the 2nd floor, the controller M is rotated to the position where it opens its contacts M3U to insert

the resistor R6 in the generator field winding to still further decelerate the car. As the car arrives within 2½ feet of the 2nd floor, the continued rotation of the controller M opens its contacts M2U thus inserting the resistor R7 in the generator field winding to further decelerate the car. As the car arrives within 2 feet of the 2nd floor, the continued rotation of the controller M opens its contacts M1U, thus inserting the resistor R8 in the generator field winding to further decelerate the car.

As the car continues up toward the 2nd floor and arrives at a point twenty inches therefrom, the up-inductor relay UF passes the lower end 15 of the inductor plate IP for the 2nd floor and thereby has its contacts UF1 closed to control the leveling in and stopping action of the car at the second floor.

The closed contacts UF1 energize the auxiliary stopping relay UE and the clutch magnet control relay H. The energized clutch magnet relay H energizes the clutch magnet CM to correctly center the controller M and also deenergizes the brake transfer relay TM which thereupon releases the brake 27 from the controller L which causes the spring 32 to apply the brake 29 to the controller M. The continued movement of the car now operates the controller L to decelerate the car in the manner previously described.

As the car decelerates to within ½ of an inch of the floor level at the 2nd floor, the up contacts UF1 on the inductor relay UF pass beyond the upper end of the inductor plate IP which causes them to open and deenergize the relays H and UE.

The deenergized relay H deenergizes the clutch magnet CM and the advance motor AM. The deenergized relay UE deenergizes the up direction switch U and the running relay 6. The deenergized relay 6 deenergizes the leveling relay 65, and the deenergized switch U deenergizes the generator field winding GF, the brake coil 15a and the control conditioning relay 32T. The deenergized brake coil causes the brake to be applied to the car, and it stops level with the 2nd floor to take on the passenger who operated the upholding button 2UB thereat. The car now stops and stands at the 2nd floor.

RELEVELING OF CAR STANDING AT 2ND FLOOR

It will be assumed now that the large number of passengers who got on at the first floor leave the car at the second floor. The decrease in load on the car causes the car, on account of cable stretch, to move upwardly ¾ of an inch above the floor level. This movement of the car causes the contacts DF1 of inductor relay DF to pass above the lower end of the inductor plate IP at the 2nd floor which causes them to close. The closing of the contacts DF1 energizes the auxiliary down stopping relay DE and the clutch magnet control relay H. The energized relay H energizes the clutch magnet CM, but this has no effect at this time.

The energized relay DE closes its contacts DE2 and opens its contacts DE1. The opening of the contacts DE1 prevents energization of the up direction switch U. The closing of the contacts DE2 energizes the down direction switch D and the running relay 6 by the circuit L+1, 17, DE2, UE2, D, 6, L-1a.

The energized down direction switch D closes its contacts D1, D2 and D3. The closed contacts D1 prepare the brake coil circuit for operation. 75 The closed contacts D2 and D3 energize the gen-

generator field winding GF to move the car downwardly.

The energized relay 6 closes its contacts 6-1, thus energizing the relay 1 by the circuit L+1, 11, 7, 6-1, H1, L-1a. The energized relay 1, 5 closes its contacts in the generator loop circuit and the brake coil circuit to energize the hoisting motor, the brake coil 15a and the control relay 32T.

The brake being released and the hoisting motor being energized, the car moves downwardly slowly, and as it gets within five-eighths inch of the floor, the inductor contacts DF1 pass below the lower end of the inductor plate IP and are opened, thereby deenergizing the auxiliary down stopping relay DE and the clutch magnet control relay H. These deenergized relays de-energize the down direction switch D, the car running relay 6 and the clutch magnet CM. The deenergized direction switch D and the running relay 6 deenergize the generator G, the brake coil 15a and the relay 32T, thus applying the brake and stopping the car level with the floor. After the expiration of one second, the deenergized control relay 32T opens its contacts 32T1, 25 and deenergizes the pre-energization relay 1 to return it to its normal condition.

The foregoing illustrates how the car will level itself with a floor when it moves a very small distance therefrom on account of the loading or unloading, affecting the stretch of the cables supporting the car.

OPERATION OF CAR FROM 2ND FLOOR TO 10TH FLOOR AND RELEVELING FROM AN OVERRUN THEREAT

It will be assumed that the up passenger at the 2nd floor upon entering the car calls for the 10th floor and that the attendant thereupon operates the stop car button 18C to cause the car to stop at the 10th floor when it arrives thereat. The operation of the button 18C sets up a stop call for the 10th floor in the same manner as was described when the car stopped at the 7th floor to take on a passenger for the 10th floor.

It will be assumed now that the attendant presses the button CS in the car to cause it to resume its up trip. The operation of the button CS energizes the starting relay 80 which in turn energizes the door closing relay 45, the up direction switch U, the running relay 6, the advance motor AM, and deenergizes the brake transfer magnet TM. This causes the car to move upwardly in the same manner as it was moved upwardly from the first floor to the 7th floor, the advance motor rotating the controllers L and M to their "on" position ready for decelerating the car at the 10th floor stop and at the same time causing the up carriage UC to move out to a position where it has a twenty foot lead on the car.

It will be assumed now that the car approaches the 10th floor and is decelerated to a stop thereat in the same manner as in the previous stopping operation at the 10th floor.

As the car arrives at a point within five-eighths inch of the 10th floor, the controller L is in its zero position, the clutch magnet CM is deenergized, the relays H, UE, U, 6, 32T, 43T and 65 are deenergized, the generator is deenergized and the brake is applied to stop the car level with the 10th floor.

It will be assumed, however, that the car overruns the floor and slides past it for, say, seven inches. As the car slides up past the floor, it moves the contacts DF1 of the down inductor

relay DF adjacent to the lower end of the inductor plate IP for the 10th floor which actuates them to their closed position, thus energizing the clutch control relay H and the auxiliary down stopping relay DE.

It should be recalled that the relay 43T is intended to distinguish between a leveling operation and a releveling operation. Since it has a time delay in dropout which may be of the order of two seconds, the relay contacts 43T1 remain open for the delay period following a deenergization of the leveling relay 43T to prevent energization of the transfer relay TM through the contacts 43T1.

The energized relay H opens its contacts H4, preventing energization of the transfer relay TM; closes its contacts H3, energizing the clutch magnet CM; and closes its contacts H2 energizing the advance motor AM. The energization of the motor AM has no effect because its resistor R44 is still included in its circuit and the car is still running upwardly and thereby rotating the controller drum L from its "on" position in the up direction and as the controller drum L continues to be rotated, it will pass its neutral point and rotate toward its "on" position for the down direction, closing its contacts L1D and L2D.

The energized relay DE energizes the down direction switch D and the car running relay 6 by the circuit L+1, 17, DE2, UE2, D, 6, L-1a.

The energized switch D closes its contacts D2 and D3 thereby energizing the generator field winding GF. The energized switch D closes its contacts D1 which reenergizes the control magnet 32T before it times out and at the same time energizes the brake coil 15a.

Inasmuch as the relay 1 has not yet been deenergized, the hoisting motor is energized and, the brake being lifted, the car is reversed and starts to level back to the 10th floor.

As the car moves downwardly it changes the direction of operation of the synchronous motor SM which, in turn, rotates the controller L in its reverse direction so that it now reverses and starts to return to its center position and in doing so reopens first its contacts L2D and then L1D thus reinserting the resistors R40 and R41 in the circuit of the generator field winding to hold down the speed of the hoisting motor. The contact L2D opens when the car is about seven inches from the floor and the contacts L1D open when the car is about three inches from the floor, thus the car is returned to the floor at a fairly rapid rate and might be said to have a rapid return.

When the car is five-eighths inch above the floor, the contacts DF1 of the inductor relay DF drop below the inductor plate IP and are thereby opened to deenergize the relays H and DE.

The deenergized relay H deenergizes the clutch magnet CM, although this is without effect at this time. The deenergized relay DE opens its contacts DE2 thereby deenergizing the down direction switch D and the running relay 6. The deenergized relay D opens its contacts D2 and D3 thereby deenergizing the generator G to stop the hoisting motor and also opens its contacts D1 to deenergize the brake coil 15a to stop the car and to deenergize the control relay 32T. The hoisting motor being deenergized and the brake being applied, the car stops level with the 10th floor.

After the expiration of approximately one second, the control relay 32T times out and opens its contacts 32T1 to deenergize the pre-energization relay 1. Later the relay 43T times out and

closes its back contacts 43T1 thus again energizing the brake transfer magnet TM to release the brake 29 and apply the brake 27, leaving the controller M free to be centered during the stop.

The foregoing operation of the apparatus indicates how a long overrun will operate the control system to produce a quick or rapid return of the car to the level of the floor at which the stop is to be made, while a slight overrun or a slight movement of the car away from the floor at which it is standing will cause the control system to make a slow return of the car to the floor level.

EXPRESS ZONE APPARATUS AND CIRCUITS IN FIGS.
23 TO 26 INCLUSIVE

In some tall buildings it is desirable to operate one bank of elevators or some of the cars in one of the banks as express cars to carry their passengers rapidly through an express zone into a high local zone of floors. The present selector may be readily adapted to such express service by the substitution of a false floor for the usual stop lugs and contacts for the express zone floors and by the addition of some express relays, with a consequent saving in parts, expense in installing and maintaining, and space for housing the selector mechanism.

In the present case the express zone will be considered as embodying the lower fourteen floors and the high zone as starting at the 15th floor and extending to the 20th floor; that is, the express car will run past the first fourteen floors to serve the 15th to 20th floors. The false floor for reducing the size of the floor selector to take care of the express zone comprises an up express lug FUN and a down express stop lug FDN to be substituted for the up stop lugs 2UN to 14UN inclusive and the down stop lugs 2DN to 14DN inclusive and a pair of up express stop contacts UEZ and UEL and a pair of down stop contacts DEZ and DEL to be substituted for the contact blocks P, S, U and D for the 2nd to 14th floors inclusive.

The contacts UEZ and UEL are mounted on the rod 55 in position to be operated by the roller 145 on the carriage UC when the carriage is moved a distance equal to a lead of 25 ft. beyond the 1st floor position of the car and below the P block of contacts for the 15th floor equal to about a ten foot movement of the car and in position to be operated by the roller 145 on the carriage. When the roller 145 closes the contacts UEZ it energizes the up pawl magnet UPP to move its pawl into stopping position against the up express lug FUN to prevent further operation of the up carriage until the car nears the end of its up movement through the express zone and approaches the 15th floor. The stopping lug FUN should be disposed on the rod 57 at a position below the stopping lug 15UN for the 15th floor approximately equal to a ten foot movement of the car.

The contacts UEL which are operated when the contacts UEZ are operated may be used for lighting a position indicator lamp (not shown) to indicate that the car is in the express zone.

The down express contacts DEZ and DEL are mounted on the rod 56 in position to be engaged by the contact roller 150 and 151 of the down selector carriage DC when it moves from the high zone into the express zone. These contacts may be located above the S block of contacts for the 15th floor approximately equal to a 25 ft. movement of the car and should be a distance

below the S block of contacts for the 1st floor equal to about a ten foot movement of the car. The contacts DEL may be used to light a down lamp (not shown) to indicate that the car is on a down trip in the express zone. The contacts DEZ are used for energizing the down pawl magnet DNP to move its down pawl into engagement with the down stopping lug FDN which should be disposed on the rod 58 in a position equal to approximately ten feet before the first floor.

An express relay ER is provided for relaying the action of the express zone contacts on the floor selector to the stop pawls on the carriages.

An express inductor relay EI is provided for releasing the floor selector carriages from the false floor stopping lugs when the car is about to complete its trip through the express zone.

The express inductor relay EI should be mounted on the car in position to be actuated by an up express plate EIUP mounted on the wall of the hatchway at a point approximately 30 1/2 ft. below the 15th floor and a down express inductor plate EIDP mounted on the wall of the hatchway approximately 30 1/2 ft. above the 1st floor.

An express time delay relay ERX having a resistor 15R and a condenser ERC to delay its drop out action for approximately 1/2 second, is provided for transferring the circuit of the express relay ER from control by the express contacts UEZ and DEZ to control by the contacts on the express inductor relay. When the express car leaves the 1st floor and its up carriage UC gets ahead of it a distance of approximately 25 ft., the carriage is stopped by the false floor and remains in its stopped position while the car moves on through the express zone to a point 30 1/2 ft. below the 15th floor where the express inductor relay meets the up express plate and is operated thereby to effect the release of the up carriage so that it will start again and run at approximately 20 ft. ahead of the car to pick up calls at the 15th to 20th floors in the usual manner.

When the express car moves downwardly from the 15th floor into the express zone, the down carriage DC is stopped by the closing of the down false floor contacts DEZ and remains thereat while the car moves down through the express zone until it gets approximately 30 1/2 ft. from the 1st floor, where the inductor relay meets the down express inductor plate and restores the down carriage to the action of the car so that it starts to move into its first floor position at its usual lead of approximately 20 ft. ahead of the car.

When the selector is adapted for express zone use, the centering plate 305 should be provided with additional centering holes 307 and 308 which will permit the centering pin 34 to lock the controller M in either its up "on" position or its down "on" position while the car is in the express zone. This is necessary because the controller must be declutched from the differential K2 while the car is in the express zone to permit the synchronous motor SM to operate freely through the differential K1, the differential K2 and the shaft 30 without effecting any operation of the selector carriages or the controllers.

OPERATION OF EXPRESS CAR

It will be assumed now that the system has been modified to enable the car to be run as an express car to the 15th floor and then as a local car from there up to the 20th floor. Under this modification the circuits shown in Fig. 23 will be

added to the control system; the circuit shown in Fig. 24 will be substituted for the hall call button circuits shown in Fig. 21; and the contacts and stopping lugs on the floor selector will be arranged as shown in Fig. 25.

It will be assumed now that a waiting up passenger at the 18th floor presses the hall button 18UB and thereby energizes the hall call registering relay 18UR to register a stop call at that floor by the circuit L+5, 18UB, 18UR, L-5 (Fig. 24). The energized relay 18UR closes its self-holding contacts 18UR1, thereby energizing the floor selector contacts 18SR so that when the car approaches the 18th floor it will pick up the stop call thereat by closing the contacts 18SR on the floor selector.

It will be assumed now that the car is standing at the lower landing, and the attendant presses the starting button CS, that the car starts in the same manner as described in the run from the 1st floor to the 7th floor, that the controllers L and M are rotated to their on position for the up direction and that the up carriage has attained a lead on the car of approximately twenty feet.

Rotation of the controller M to its full on position has closed its contacts M8U to prepare a circuit for the express relay ER. When the carriage has advanced a distance equal to approximately twenty-five feet from the 1st floor, its roller 145 engages the express contacts UEZ and UEL mounted on the supporting shaft 55 and closes them.

The closed contacts UEZ energize the express relay ER by the circuit L+4, M8U, UEZ, ERX2, EIU, W8, ER, L-4 (Fig. 23). The energized relay ER closes its contacts ER1 to ER5, inclusive. The closed contacts ER1 energize the clutch magnet CM by the circuit L+1b, ER1, CM, L-1. The energized clutch magnet opens the clutch 26 to hold the controller M in its present position while the car is being expressed and also moves the locking pin 34 into the centering hole 308 to hold the controller M in its up "on" position and lock it against movement while the car is passing through its express run.

The closed contacts ER3 provide a self-holding circuit for the relay ER. The contacts ER4 energize the express inductor relay EI by the circuit L+4, ER4, EI, L-4. The inductor relay EI will not be operated until the car nears the 15th floor and carries the relay to the inductor plate EIUP.

The closed contacts ER5 energize the express time delay relay ERX by the circuit L+4, ER4, ERX, ER5, L-4.

The closed contacts ER2 energize the up carriage pawl magnet UPP by the circuit: L+3, ER2, 45-2, L1OU, UPP, L-3. The energized magnet UPP attracts its armature 114, thereby moving the pawl 110 outwardly so that the roller 121 engages the up-express stop lug FUN and locks the up carriage against further upward movement from its false floor position until the car nears the 15th floor.

The energized relay ERX closes its contacts ERX3 and opens its contacts ERX1 and ERX2. The opened contacts ERX1 eliminate the holding circuit for the up pawl magnet UPP, leaving it under the control of the contacts ER2. The contacts ERX2 open in one circuit of the relay ER, leaving it under the control of its self-holding circuit and the inductor relay EI. The closed contacts ERX3 provide a holding circuit for the relay ERX and also for the relay EI which will

be held until the inductor relay contacts are operated to deenergize the relay ER.

Since the car is moving upwardly, and the up carriage is stalled against the lug FUN, the synchronous motor SM operated by the car now drives through the differential K1 against the torque of the advance motor AM and through the differential K2 to the clutch 26 associated with the controller M. However, the clutch 26 is opened because its magnet CM is energized and the brake 27 is applied to the controller L. Hence, the motion, due to the action of the synchronous motor SM, ends with the open clutch 26 and is not transmitted to either controller while the car is running through the low zone.

It will be assumed now that the car approaches to within approximately 30 $\frac{1}{2}$ feet of the fifteenth floor, and thereby moves the inductor relay EI adjacent to the express inductor plate thereat, the influence of which causes the contacts EIU on the inductor relay to open and thus deenergize the express relay ER.

The deenergized relay ER opens its contacts ER1, ER2 and ER5. The opened contacts ER2 deenergize the up pawl magnet UPP which releases its armature 114 so that the spring 118 moves the pawl arm 110 and roller 121 away from the up-stopping lug FUN. This leaves the up carriage free to resume its upward movement with a 20-foot lead on the car, and while it is yet a distance equivalent to 10 feet from the fifteenth floor position on the floor selector.

The opening of the contacts ER1 deenergizes the clutch magnet CM so that the clutch 26 is again closed. With the controller M locked in its outermost position, the advance motor AM is stalled. Hence the movement of the car transmitted through the synchronous motor SM now moves the carriage UC upwardly with the upward movement of the car and with a 20-foot lead on the car. As the up carriage resumes its upward movement, its roller 145 leaves the express contacts UEZ and they open, returning the circuit of the relay ER to normal condition.

After the expiration of a time delay of say $\frac{1}{16}$ second, the time delay relay ERX opens its contacts ERX3, thus deenergizing itself and the inductor relay EI. The deenergized relay ERX also closes its contacts ERX1 to restore the holding circuit for the pawl magnets UPP and DNP.

As the up carriage arrives at its position corresponding to the 18th floor, the rollers 150 and 151 on the down carriage close the contacts 18S4, 438 in the same manner as that relay was energized in the first stop at the 7th floor, hereinbefore described. The energization of the stopping relay 438 energizes the up-stopping pawl magnet UPP and causes the car to slow down and stop at the 18th floor in the same manner as it was caused to slow down and stop at the 7th floor when the stopping relay 438 was energized as the car approached that floor.

The foregoing operation illustrates how the selector may be set up without any stopping lugs or contacts for the floors between the lower landing and the group of upper floors to be served by an express car, and also how the up carriage will be run out ahead of the car while it is getting up to normal speed and then will be locked against further movement while the car traverses the express zone and gets ready to enter the upper local zone which it desires to serve.

The operation for the down direction for the zone car is made in a similar manner to that de-

scribed above for the up direction; with the false selector floor indicated by the contacts DEZ and DEL on the floor selector and the stopping lug FDN mounted on the floor selector to effect the stopping of the down carriage and stalling it against further movement while the car proceeds, downwardly from the fifteenth floor and approaches to within approximately 30½ feet of the first floor; at which point the inductor relay EI will come opposite the down express inductor plate EIDP and be operated to restore the express relays and unlock the down carriage so that it can move ahead of the car into the first floor where the car will be stopped by the usual limit switches (not shown) or by those set up for the first floor hall button.

By the foregoing arrangement of the system for express operation, it will be observed that much expense and space may be saved by modifying the floor selector and circuits thus simplifying the apparatus to be installed and maintained and decreasing considerably the amount of space which would otherwise be required for a floor selector having contacts for every floor.

Although I have illustrated and described only one specific embodiment of my invention for normal elevator service and a modification thereof for use with express elevators, I desire it to be understood that many modifications thereof and changes therein may be made without departing from the spirit and scope of my invention.

I claim as my invention:

1. In an elevator system for a car operable past a plurality of floors, a motor for driving the car, a generator for energizing the motor, said generator having a field winding, a starting control means for starting the car, starting means responsive to operation of the starting control means for energizing the field winding and starting the car, said starting means including timing means energized from a source independent of the field energization for accelerating the car in predetermined timed steps, a stopping means for each floor for initiating a stopping operation of the car at that floor, a controller means for decelerating the car, means responsive to operation of a stopping means and to movement of the car for operating the controller means to decelerate the car to a predetermined stopping speed in accordance with the movement of the car, a control device at each of the floors, a control unit disposed on the car, said control unit, when suitably conditioned, cooperating with the control devices a predetermined distance from each of the floors for effecting a control operation at a predetermined distance from any of the floors, and means responsive to operation of the controller means and to a control operation initiated by the control device for the floor of the operated stopping means for stopping the car at that floor.

2. In an elevator system a car for serving a plurality of floors, a hoisting motor for the car, controller means for decelerating the hoisting motor, a starting means for the motor, a stopping means for the car, an advance motor, means responsive to operation of the starting means for energizing the hoisting motor and for causing the advance motor to move the controller means toward "on" position, and timed control devices successively responsive to successive degrees of operation of the controller means toward "on" position for accelerating the hoisting motor at predetermined intervals, means responsive to operation of the stopping means and to movement of the car for causing operation of the controller

means to "off" position by and in accordance with the movement of the car for decelerating the hoisting motor.

3. In an elevator system, a car for serving a plurality of floors, a hoisting motor for the car, controller means for decelerating the hoisting motor, a starting means for the motor, floor stopping devices for the car, an advance motor, means responsive to operation of the starting means for energizing the hoisting motor and for causing the advance motor to move the controller means toward "on" position, means responsive to operation of a stopping device for a floor and to the approach of the car to that floor for causing operation of the controller means toward "off" position by the car in accordance with the movement of the car, and inductor means responsive to decelerating operation of the controller means and to the approach of the car to within a predetermined distance of the floor for which the stop device has been operated for deenergizing the hoisting motor to stop the car.

4. In an elevator controller for a car operable past a plurality of floors and for stopping said car at said floors in response to actuated floor push buttons, the combination of starting means for said car and stopping means; a floor selector comprising coarse speed reducing means and fine speed reducing means, both operable in response to car motion, means responsive to the actuation of a push button at a floor and the approach of said car to a predetermined distance of said floor for rendering effective said coarse speed reducing means, and inductor means mounted on the car and responsive to the approach of said car to a predetermined distance of said floor for rendering ineffective said coarse speed reducing means and for rendering effective said fine speed reducing means and said stopping means.

5. In an elevator system, a car for serving a plurality of floors, a hoisting motor for the car, a starting means for the hoisting motor, stop devices for the floors, a power means operable by the car in accordance with the movement of the car, an advance motor of less power than the power means, a floor selector having an up carriage and a down carriage movably mounted thereon, a controller means including two controllers for causing deceleration and stopping of the car, a differential connecting the carriages differentially to the advance motor and the power means, a differential connecting the advance motor differentially to the controllers, said differentials being effective for advancing the carriages to a lead position with respect to the car and for moving the controller means toward "on" position when the starting means is operated to start the car, for moving the carriages in accordance with the movement of the car while it operates at its normal speed, and for operating the controller means to decelerate the car and cause it to stop at a floor, means responsive to operation of a stop device and to movement of the carriages for stopping the carriages, and means responsive to stopping of the carriages and to further movement of the car for initiating the decelerating and stopping operation of the controller means.

6. In an elevator system a car for serving a plurality of floors, a hoisting motor for the car, a starting means for the hoisting motor, stop devices for the floors, a power means operable by the car in accordance with the movement of the car, an advance motor of less power than the power means and operable independently of the

45

power means, a controller means including two controllers for decelerating the hoisting motor, selector stopping mechanism, a differential connecting the stopping mechanism differentially to the advance motor and the power means, a differential connecting the advance motor differentially to the controllers, means responsive to operation of the starting means for first starting the advance motor and then starting the hoisting motor, whereby the advance motor will operate 10 the differentials to move the controller means toward "on" position, means responsive to operation of a stop device and to movement of the car for causing the differentials to be operated by the car to move the controller means toward "off" 15 position in accordance with the movement of the car, and means responsive to the movement of the controller means toward "off" position and to movement of the car to within a predetermined distance of the floor of the operated stop device for deenergizing the hoisting motor to stop the car.

7. In an elevator system, a car for serving a plurality of floors, a hoisting motor for the car, a starting means for the hoisting motor, stop devices for the floors, a power means operable by the car in accordance with the movement of the car, an advance motor of less power than the power means and operable independently of the power means, a main controller for decelerating the hoisting motor in coarse steps, a leveling controller for decelerating the hoisting motor in fine steps, differential means connecting the power means, the advance motor, and the controllers, means responsive to operation of the starting means for first starting the advance motor and then starting the hoisting motor, whereby the advance motor will operate the differential means to move first the leveling controller and then the main controller toward "on" position, means responsive to operation of a stop device and to movement of the car for causing the differential means to be operated by the car to move first the main controller and then the leveling controller toward "off" position in accordance with the movement of the car, and means responsive to the movement of the controllers toward "off" position and to movement of the car to within a predetermined distance of the floor of the operated stop device for deenergizing the hoisting motor to stop the car.

8. In an elevator system for a car serving a plurality of floors, a hoisting motor for the car, a starting means for the hoisting motor, stop devices for the floors, a power means operable by the car in accordance with the movement of the car, an advance motor of less power than the power means and operable independently of the power means, a floor selector having an up carriage and a down carriage movably mounted thereon, a controller means including two controllers for decelerating the hoisting motor, a differential connecting the carriages differentially to the advance motor and the power means, a differential connecting the advance motor differentially to the controllers, means responsive to operation of the starting means for first starting the advance motor and then starting the hoisting motor, whereby the advance motor will operate the differentials to give the carriages a lead ahead of the car and move the controller means toward "on" position, means responsive to operation of a stop device and to movement of the carriages for stopping the carriages to cause the differentials to be operated by the car to move

46

the controller means toward "off" position in accordance with the movement of the car, and means responsive to the movement of the controller means toward "off" position and to movement of the car to within a predetermined distance of the floor of the operated stop device for deenergizing the hoisting motor to stop the car.

9. In an elevator system a car for serving a plurality of floors divided into an express zone and a high local zone, a hoisting motor for the car, a starting means for the hoisting motor, stop devices for the floors, a power means operable by the car in accordance with the movement of the car, an advance motor of less power than the power means and operable independently of the power means, a floor selector divided into an express zone and a high local zone and having an up carriage and a down carriage movably mounted thereon, a controller means for decelerating the hoisting motor, differential means connecting the power means, the advance motor, the carriages, and the controller means, means responsive to operation of the starting means for first starting the advance motor and then starting the hoisting motor, whereby the advance motor will operate the differential means to give the carriages a lead ahead of the car and move the controller means toward "on" position, and whereby the power means will operate the differential means to move the carriages in accordance with the movement of the car when it runs at normal speed, means responsive to movement of the car through its express zone for stopping the carriages in the express zone of the selector while the car moves through its express zone, means responsive to the approach of the car to the end of its express zone for releasing the carriages to move in accordance with the movement of the car, means responsive to operation of a stop device and to movement of the carriages in the local zone of the selector for stopping the carriages to cause the differential means to be operated by the car to move the controller means toward "off" position for decelerating the hoisting motor in accordance with the movement of the car, and means responsive to the movement of the controller means toward "off" position and to movement of the car to within a predetermined distance of the floor of the operated stop device for deenergizing the hoisting motor to stop the car.

10. In an elevator system, a car for serving a plurality of floors, a hoisting motor for the car, a starting means for the hoisting motor, stop devices for the floors, a power means operable by the car in accordance with the movement of the car, an advance motor of less power than the power means and operable independently of the power means, a floor selector having an up carriage and a down carriage movably mounted thereon, a controller means including two controllers for decelerating the hoisting motor, a differential connecting the carriages differentially to the advance motor and the power means, a differential connecting the advance motor differentially to the controllers, means responsive to operation of the starting means for starting the advance motor to operate the differentials to give the carriages a lead ahead of the car and move the controller means toward "on" position, means responsive to operation of the starting means for energizing the hoisting motor, means responsive to operation of a stop device and to movement of the carriages for stopping the carriages whereby further movement of the car will

cause the differentials to move the controller means toward "off" position in accordance with the movement of the car, and means responsive to the movement of the controller means toward "off" position and to movement of the car to within a predetermined distance of the floor of the operated stop device for deenergizing the hoisting motor to stop the car.

11. In an elevator system a car for serving a plurality of floors, a hoisting motor for the car, a starting means for the hoisting motor, stop devices for the floors, a power means operable by the car in accordance with the movement of the car, an advance motor of less power than the power means and operable independently of the power means, a floor selector having an up carriage and a down carriage movably mounted thereon, a plurality of controllers for decelerating the hoisting motor, a first differential connecting the power means, the advance motor and the carriages, a second differential connecting the first differential, and the controllers, means responsive to operation of the starting means for first starting the advance motor and then starting the hoisting motor, whereby the advance motor will operate the differentials to give the carriages a lead ahead of the car and move the controllers toward "on" position, means responsive to operation of a stop device and to movement of the carriages for stopping the carriages to cause the differentials to be operated by the car to move the controllers toward "off" position in sequence and in accordance with the movement of the car, and means responsive to the movement of the controllers toward "off" position and to movement of the car to within a predetermined distance of the floor of the operated stop device for deenergizing the hoisting motor to stop the car.

12. In an elevator system, a car disposed in a hatchway for serving a plurality of floors, a hoisting motor for the car, a starting means for said motor, stop devices at the floors and in the car, a first differential having an input member, an output member, and an input-output member, a power means operable by the car in accordance with the movement of the car for operating the input member, an advance motor of less power than the power means and having its shaft connected to the input-output member, a second differential having a driving member connected for operation by the input-output member, and having a first driven member and a second driven member, a floor selector for connecting signal and control circuits for the car in accordance with the position and direction of the car, said selector having an up carriage and a down carriage movably mounted thereon and connected for operation by the output member, a main controller operable by the first driven member for decelerating the hoisting motor, a leveling controller operable by the second driven member for decelerating the hoisting motor, means responsive to operation of the starting means for starting the advance motor to move the leveling controller to its "on" position, and to move the carriages to a lead position ahead of the car, means responsive to movement of the leveling controller to its "on" position for rendering that controller inoperable and rendering the main controller operable, means responsive to operation of the starting means for energizing the hoisting motor and for reenergizing the advance motor to operate the main controller toward its "on" position and to restart the carriages toward their normal lead position ahead of the car, means responsive to

the operation of a stop device for a floor and to movement of the carriages for returning the operated stop device to its normal condition, and for stopping the carriage for the direction of operation of the car so that further movement of the car will move the main controller toward its "off" position, inductor means responsive to operation of the main controller toward its "off" position and to movement of the car to within a predetermined distance of the floor of the operated stop device for rendering the main controller inoperative and the leveling controller operative by the car, and means responsive to operation of the leveling controller, operation of the inductor means and the approach of the car to within a predetermined distance of the floor of the operated stop device for deenergizing the hoisting motor.

13. In an elevator system, a car disposed in a hatchway for serving a plurality of floors, a hoisting motor for the car, a starting means for said motor, stop devices at the floors and in the car, a signal device at each floor, a first differential having an input member, an output member, and an input-output member, a power means operable by the car in accordance with the movement of the car for operating the input member, an advance motor of less power than the power means and having its shaft connected to the input-output member, a second differential having a driving member connected for operation by the input-output member, and having a first driven member and a second driven member, a floor selector having an up carriage and a down carriage movably mounted on the selector and connected for operation by the output member, a main controller disposed for operation by the first driven member, a leveling controller connected to the second driven member, a brake for preventing operation of the main controller, a brake for preventing operation of the leveling controller, means responsive to operation of the starting means for starting the advance motor to move the leveling controller to its "on" position, and to move the carriages to a lead position ahead of the car, means responsive to movement of the leveling controller to its "on" position for deenergizing the advance motor and for applying the leveling controller brake and releasing the main controller brake, means responsive to operation of the starting means for energizing the hoisting motor and for reenergizing the advance motor to operate the main controller toward its "on" position and to restart the carriages toward their normal lead position ahead of the car, means responsive to the operation of a stop device for a floor and to movement of the carriages for returning the operated stop device to its normal condition, for operating the signal device at the floor of the operated stop device, and for stopping the carriage for the direction of operation of the car so that further movement of the car will cause movement of the main controller from its forward position to its "off" position to decelerate the hoisting motor in accordance with the movement of the car, inductor means responsive to operation of the main controller toward its "off" position and to movement of the car to within a predetermined distance of the floor of the operated stop control device for rendering the main controller inoperative and the leveling controller operative by the second differential, so that further movement of the car will operate the leveling controller to further decelerate the hoisting motor in accordance with the movement of the car, and means re-

sponsive to operation of the leveling controller, operation of the inductor means and the approach of the car to within a predetermined distance of the floor of the operated stop device for de-energizing the hoisting motor to stop the car at said floor.

14. In an elevator system, a car disposed in a hatchway for serving a plurality of floors, a hoisting motor for the car, a starting means for said motor, an up hall stop device and a down hall stop device at each floor, a car stop device in the car for each floor, a signal device at each floor, a first differential having an input member, an output member, and an input-output member, a power means operable by the car in accordance with the movement of the car for operating the input member, an advance motor of less power than the power means and having its shaft connected to the input-output member, a second differential having a driving member connected for operation by the input-output member, and having a first driven member and a second driven member, a floor selector having an up carriage and a down carriage movably mounted thereon and connected for operation by the output member, a main controller disposed for operation by the first driven member, a leveling controller connected to the second driven member, a brake for preventing operation of the main controller, a brake for preventing operation of the leveling controller, a clutch disposed between the main controller and the first driven member, means responsive to operation of the starting means for starting the advance motor to move the leveling controller to its "on" position, and to move the carriages to a lead position ahead of the car, means responsive to movement of the leveling controller to its "on" position for deenergizing the advance motor and for applying the leveling controller brake and releasing the main controller brake, means responsive to operation of the starting means for energizing the hoisting motor to move the car and for reenergizing the advance motor to operate the main controller toward its "on" position and to restart the carriages toward their normal lead position ahead of the car, means for limiting the "on" movement of the main controller to stall the advance motor, whereby further movement of the car maintains the carriages in their lead position ahead of the car, a pawl mounted on each carriage, a pawl magnet for each pawl, means responsive to the operation of a stop device for a floor and to movement of the carriages for energizing the pawl magnet on the selector carriage for the direction of operation of the car to operate its pawl to lock that carriage against further movement whereby the further movement of the car operates the first differential to move the main controller from its forward position to its "off" position in accordance with the movement of the car to decelerate the hoisting motor in accordance with the movement of the car, means responsive to operation of the pawl for returning the operated stop device to its normal condition and for operating the signal device at the floor of the operated stop device, inductor means responsive to operation of the main controller to its "off" position and to movement of the car to within a predetermined distance of the floor of the operated stop control device for opening the clutch and operating the brakes to render the main controller inoperative and the leveling controller operative by the second differential, whereby further movement of the car will operate the leveling controller to further decelerate

the hoisting motor in accordance with the movement of the car, and means responsive to operation of the leveling controller, operation of the inductor means and the approach of the car to within a predetermined distance of the floor of the operated stop device for deenergizing the hoisting motor to stop the car at said floor.

15. In an elevator system, a car disposed in a hatchway for serving a plurality of floors, a hoisting motor for the car, a starting means for said motor, an up hall stop device and a down hall stop device at each landing, a plurality of car stop devices in the car, one for each floor, a signal device at each floor, a first differential having an input member, an output member, and an input-output member, a power means operable by the car in accordance with the movement of the car for operating the input member, an advance motor of less power than the power means and having its shaft connected to the input-output member, a second differential having a driving member connected for operation by the input-output member, and having a first driven member and a second driven member, a floor selector having an up carriage and a down carriage movably mounted on the selector and connected for operation by the output member, a main controller disposed for operation by the first driven member, a leveling controller connected to the second driven member, a brake for preventing operation of the main controller, a brake for preventing operation of the leveling controller, a clutch disposed between the main controller and the first driven member, a clutch magnet for opening the clutch, means responsive to operation of the starting means for starting the advance motor to move the leveling controller to its "on" position, and to move the carriages to a lead position ahead of the car, means responsive to movement of the leveling controller to its "on" position for deenergizing the advance motor and for applying the leveling controller brake and releasing the main controller brake, means responsive to operation of the starting means for energizing the hoisting motor and for reenergizing the advance motor to operate the main controller toward its "on" position and to restart the carriages toward their normal lead position ahead of the car, means for limiting the "on" movement of the main controller to stall the advance motor, whereby further movement of the car maintains the carriages in their lead position ahead of the car, a pawl mounted on each carriage, a pawl magnet for each pawl, means responsive to the operation of a stop device for a floor and to movement of the carriages for energizing the pawl magnet on the selector carriage for the direction of operation of the car to operate its pawl to lock that carriage against further movement whereby the further movement of the car operates the first differential to physically reverse the advance motor and move the main controller from its forward position to its "off" position in accordance with the movement of the car to decelerate the hoisting motor in accordance with the movement of the car, means responsive to operation of the pawl for returning the operated stop device to its normal condition and for operating the signal device at the floor of the operated stop device, an inductor plate mounted on the hatchway wall adjacent to each floor, and an inductor relay for each direction of operation mounted on the car in position to be operated, when energized, by the next inductor plate to which they are moved,

means responsive to decelerating movement of the main controller for energizing the inductor relays, a centering device for the main controller, means responsive to movement of the inductor relay for the direction of the car by the car to the presence of the inductor plate at the floor of the operated stop device for energizing the clutch magnet to disconnect the main controller from the first driven member and to operate the centering device to center it in its "off" position, and for applying the main controller brake and releasing the leveling controller brake whereby further movement of the car operates the leveling controller from its "on" to its "off" position, to further decelerate the hoisting motor in accordance with the movement of the car, means responsive to a predetermined decelerating movement of the leveling controller for opening the door at the floor of the operated stop device, and means responsive to the operation of the leveling controller and to the car moving the inductor relay for the direction of the car beyond the inductor plate for the floor of the operated stop call device for deenergizing the hoisting motor to stop the car, and for deenergizing the clutch magnet.

16. In an elevator system, a car disposed in a hatchway for serving a plurality of floors, a hoisting motor for the car, a starting means for said motor, an up hall stop device and a down hall stop device at each landing, a plurality of car stop devices in the car, one for each floor, a signal device at each floor, a first differential having an input member, an output member, and an input-output member, a power means operable by the car in accordance with the movement of the car for operating the input member, an advance motor of less power than the power means and having its shaft connected to the input-output member, a second differential having a driving member connected for operation by the input-output member, and having a first driven member and a second driven member, a floor selector having an up carriage and a down carriage movably mounted on the selector and connected for operation by the output member, a main controller disposed for operation by the first driven member, a leveling controller connected to the second driven member, a main controller brake on the first driven member, a leveling controller brake on the second driven member, a transfer magnet for controlling the brakes, a clutch disposed between the main controller and the first driven member, a clutch magnet for opening the clutch, a door for each floor landing, means responsive to operation of the starting means for starting the advance motor to move the leveling controller to its "on" position and to move the carriages to a lead position ahead of the car and for closing the door, means responsive to movement of the leveling controller to its "on" position for deenergizing the advance motor and for energizing the transfer magnet to apply the leveling controller brake and release the main controller brake, means responsive to the closing of the door for reenergizing the advance motor to operate the main controller toward its "on" position, and to restart the carriages toward their normal lead position ahead of the car, and for starting the hoisting motor, means for limiting the "on" movement of the main controller to stall the advance motor whereby further movement of the car maintains the carriages in their lead ahead of the car, means responsive to movement of the

5 main controller to its full "on" position for reducing the torque of the advance motor, a pawl mounted on each carriage a pawl magnet for each pawl, means responsive to the operation of a stop device for a floor and to movement of the carriages for energizing the pawl magnet on the selector carriage for the direction of operation of the car to operate its pawl to lock that carriage against further movement whereby the further movement of the car operates the first differential to physically reverse the advance motor and operate the main controller from its forward position to its "off" position in accordance with the movement of the car and thereby decelerate the hoisting motor in accordance with the movement of the car, means responsive to operation of the pawl for returning the operated stop device to its normal condition, and for operating the signal device at the floor of the operated stop device, means responsive to energization of the pawl magnet for reducing the torque of the advance motor if not already reduced, an inductor plate mounted on the hatchway wall adjacent to each floor, and an inductor relay for each direction of operation mounted on the car in position to be operated, when energized, by the next inductor plate to which they are moved, means responsive to decelerating operation of the main controller for energizing the inductor relays, a centering device for the main controller, and means responsive to movement of the inductor relay for the direction of the car by the car to the presence of the inductor plate at the floor of the operated stop device for energizing the clutch magnet to disconnect the main controller from the first driven member and to operate the centering device to center it in its "off" position, and for deenergizing the brake transfer magnet to apply the main controller brake and release the leveling controller brake whereby further movement of the car operates the leveling controller from its "on" to its "off" position, to further decelerate the hoisting motor in accordance with the movement of the car to a predetermined stopping speed.

17. In an elevator system, a car disposed in a hatchway for serving a plurality of floors, a hoisting motor for the car, a starting means for said motor, an up hall stop device and a down hall stop device at each landing, a plurality of car stop devices in the car, one for each floor, a signal device at each floor, a first differential having an input member, an output member, and an input-output member, a power means operable by the car in accordance with the movement of the car for operating the input member, an advance motor of less power than the power means and having its shaft connected to the input-output member, a second differential having a driving member connected for operation by the input-output member, and having a first driven member and a second driven member, a floor selector having an up carriage and a down carriage movably mounted on the selector and connected for operation by the output member, a main controller disposed for operation by the first driven member, a leveling controller connected to the second driven member, a main controller brake on the first driven member, a leveling controller brake on the second driven member, a transfer magnet for controlling the brakes, a clutch disposed between the main controller and the first driven member, a clutch magnet for opening the clutch, a door for each floor land-

ing, means responsive to operation of the starting means for deenergizing the transfer magnet to release the leveling controller brake and apply the main controller brake and for starting the advance motor to move the leveling controller to its "on" position and to move the carriages to a lead position ahead of the car, and for closing the door at the car, means responsive to movement of the leveling controller to its "on" position for deenergizing the advance motor and for energizing the transfer magnet to apply the leveling controller brake and release the main controller brake, means responsive to operation of the starting means and to the closing of the door for starting the hoisting motor and for reenergizing the advance motor to operate the main controller toward its "on" position and to restart the carriages toward their normal lead position ahead of the car, time control means associated with the main controller for accelerating the hoisting motor at predetermined time intervals, means for limiting the "on" movement of the main controller to stall the advance motor whereby further movement of the car maintains the carriages in their lead ahead of the car, means responsive to movement of the main controller to its full "on" position for reducing the torque of the advance motor, a pawl mounted on each carriage, a pawl magnet for each pawl, means responsive to operation of a stop device for a floor and to movement of the carriages for energizing the pawl magnet on the selector carriage for the direction of operation of the car to operate its pawl to lock that carriage against further movement whereby the further movement of the car operates the first differential to physically reverse the advance motor and operate the main controller from its forward position to its "off" position in accordance with the movement of the car and thereby decelerate the hoisting motor in accordance with the movement of the car, means responsive to operation of the pawl for returning the operated stop device to its normal condition, and for operating the signal device at the floor of the operated stop device, an inductor plate mounted on the hatchway wall adjacent to each floor, and an inductor relay for each direction of operation mounted on the car in position to be operated, when energized, by the next inductor plate to which they are moved, means responsive to decelerating operation of the main controller for energizing the inductor relays, a centering device for the main controller, means responsive to movement of the energized inductor relay for the direction of the car by the car to the presence of the inductor plate at the floor of the operated stop device for energizing the clutch magnet to disconnect the main controller from the first driven member and to operate the centering device to center it in its "off" position, and for deenergizing the brake transfer magnet to apply the main controller brake and release the leveling controller brake whereby further movement of the car operates the leveling controller from its "on" to its "off" position, to further decelerate the hoisting motor in accordance with the movement of the car, means responsive to a predetermined decelerating movement of the leveling controller for starting the door at the floor of the operated stop device to open, means responsive to the car moving the inductor relay for the direction of the car beyond the inductor plate for the floor of the operated stop call device and to the opening of the door for deenergizing the hoisting

motor to stop the car, and for deenergizing the clutch magnet.

18. In an elevator system, a car disposed in a hatchway for serving a plurality of floors, a hoisting motor for the car, a starting means for said motor, an up hall stop device and a down hall stop device at each landing, a plurality of car stop devices in the car, one for each floor, a signal device at each floor, a first differential having an input member, an output member, and an input-output member, a power means operable by the car in accordance with the movement of the car for operating the input member, an advance motor of less power than the power means and having its shaft connected to the input-output member, a floor selector having an up carriage and a down carriage movably mounted on the selector and connected for operation by the output member, a second differential having a driving member connected for operation by the input-output member, and having a first driven member and a second driven member, a main controller disposed for operation by the first driven member, a single adjustable up limit device and a single adjustable down limit device associated with the main controller for setting the normal high speed of the car, the stopping distance of the car and the floor lantern lead to any desired values, a leveling controller connected to the second driven member, a main controller brake on the first driven member, a leveling controller brake on the second driven member, a transfer magnet for controlling the brakes, a clutch disposed between the main controller and the first driven member, a clutch magnet for opening the clutch, a door for each floor landing, means responsive to operation of the starting means for deenergizing the transfer magnet to release the leveling controller brake and apply the main controller brake, and for starting the advance motor to move the leveling controller to its "on" position, and to move the carriages to a lead position ahead of the car, and for closing the door at the car, means responsive to movement of the leveling controller to its "on" position for deenergizing the advance motor and for energizing the transfer magnet to apply the leveling controller brake and release the main controller brake, means responsive to operation of the starting means and to the closing of the door for starting the hoisting motor and for reenergizing the advance motor to operate the main controller toward its "on" position, and to restart the carriages toward their normal lead position ahead of the car, means responsive to the operation of the main controller for accelerating the hoisting motor, time control means for limiting the acceleration of the hoisting motor to predetermined time intervals, means for limiting the "on" movement of the main controller to stall the advance motor, whereby further movement of the car maintains the carriages in their lead ahead of the car, means responsive to movement of the main controller to its full "on" position for reducing the torque of the advance motor, a pawl mounted on each carriage, a pawl magnet for each pawl, means responsive to the operation of a stop device for a floor and to movement of the carriages for energizing the pawl magnet on the selector carriage for the direction of operation of the car to operate its pawl to lock that carriage against further movement whereby the further movement of the car operates the first differential to physically reverse the advance motor and operate the main controller from its forward position to its

"off" position in accordance with the movement of the car and thereby decelerate the hoisting motor in accordance with the movement of the car, means responsive to operation of the pawl for returning the operated stop device to its normal condition, and for operating the signal device at the floor of the operated stop device, means responsive to energization of the pawl magnet for reducing the torque of the advance motor if not already reduced, an inductor plate mounted on the hatchway wall adjacent to each floor, and an inductor relay for each direction of operation mounted on the car in position to be operated, when energized, by the next inductor plate to which they are moved, means responsive to decelerating operation of the main controller for energizing the inductor relays, a centering device for the main controller, means responsive to movement of the inductor relay for the direction of the car by the car to the presence of the inductor plate at the floor of the operated stop device for energizing the clutch magnet to disconnect the main controller from the first driven member and to operate the centering device to center it in its "off" position, and for deenergizing the brake transfer magnet to apply the main controller brake and release the leveling controller brake whereby further movement of the car operates the leveling controller from its "on" to its "off" position, to further decelerate the hoisting motor in accordance with the movement of the car, means responsive to a predetermined decelerating movement of the leveling controller for starting the door at the floor of the operated stop device to open, means responsive to the car moving the inductor relay for the direction of the car beyond the inductor plate for the floor of the operated stop call device and to the opening of the door for deenergizing the hoisting motor to stop the car, and for deenergizing the clutch magnet, means responsive to the car moving the inductor relay for the opposite direction to the plate if the car overruns the floor, for energizing the clutch magnet and reversing the hoisting motor to level the car with the floor and responsive to the car returning said opposite inductor relay to its position off the plate for deenergizing the clutch magnet and deenergizing the hoisting motor to stop the car, and means responsive to the opening of the door and a predetermined time interval thereafter for reenergizing the brake transfer magnet to release the main controller brake and apply the leveling controller brake, so that movement of the car away from the floor when the hoisting motor is deenergized may operate the inductor relays to return the car to the floor at slow speed without operating the controllers.

19. In an elevator mechanism for a car serving a plurality of floors, a hoisting motor for operating the car, a power means operable by the car in accordance with the movement of the car, an advance motor of less power than the power means and operable independently thereof, a controller means including a pair of controllers for decelerating the hoisting motor when a stop is to be made, stopping means including movable carriage means for determining at which floors a car stop is to be made, a differential for connecting the movable carriage differentially to the advance motor and the power means, and a differential for connecting the advance motor differentially to the controllers for moving the controller means to "on" position when the advance motor is started, and for moving the con-

troller means to "off" position when the car is to be stopped.

20. In an elevator mechanism for a car serving a plurality of floors, a hoisting motor for the car, a power means operable by the car in accordance with the movement of the car, an advance motor of less power than the power means and operable independently of the power means, a main controller for decelerating the hoisting motor in coarse steps, a leveling controller for decelerating the hoisting motor in fine steps, and differential means connecting the power means, the advance motor, and the controllers for moving first the leveling controller and then the main controller toward "on" position when the advance motor is operated, and for moving first the main controller and then the leveling controller toward "off" position when the car is to be stopped.

21. In an elevator mechanism for a car serving a plurality of floors, a hoisting motor for operating the car, a differential mechanism having a pair of output driven members, a main controller connected for operation by one of the driven members, a leveling controller connected for operation by the other driven member, a brake mechanism for controlling the operation of the driven members, an advance motor for driving the differential mechanism to move the controllers sequentially toward their "on" position when the car is being started, and a power means operable by the car in accordance with the movement of the car for driving the differential mechanism to move the controllers sequentially to their "off" position when the car is to be stopped.

22. In an elevator mechanism for a car serving a plurality of floors, a hoisting motor for operating the car, a differential mechanism having a pair of output driven members, a main controller connected for operation by one of the driven members, a leveling controller connected for operation by the other driven member, an advance motor for driving the differential mechanism to move the controllers sequentially toward their "on" position when the car is being started, and a power means operable by the car in accordance with the movement of the car for driving the differential mechanism to move the controllers sequentially to their "off" position when the car is to be stopped.

23. In an elevator system, a car for serving a plurality of floors, a hoisting motor for the car, a controller for decelerating the hoisting motor, a starting means for the car, stopping devices for the car, means responsive to operation of the starting means for energizing the motor to start the car and for moving the controller toward its "on" position, means responsive to operation of a stopping device for a floor and to movement of the car for moving the controller toward its "off" position, and means responsive to movement of the controller to approximately its "off" position and independent of the hoisting motor for accurately centering the controller in its "off" position.

24. In an elevator system, a car for serving a plurality of floors, a hoisting motor for the car, a controller for decelerating the hoisting motor, said controller having a conical depression in its frame, a starting means for the car, stopping devices for the car, means responsive to operation of the starting means for energizing the motor to start the car and for moving the controller toward its "on" position, means responsive to operation of a stopping device for a floor and to

movement of the car for moving the controller toward its "off" position, a centering pin slidably mounted adjacent to the controller, and means responsive to movement of the controller to approximately its "off" position for disconnecting it from operation by movement of the car and for moving the centering pin into the conical depression to accurately center the controller in its "off" position.

25. In an elevator system a car for serving a plurality of floors, a hoisting motor for the car, a controller for decelerating the hoisting motor, a driving means for the controller, a clutch between the driving means and the controller, a centering device for the controller, a starting means for the car, stopping devices for the car, means responsive to operation of the starting means for energizing the motor to start the car and for operating the driving means to move the controller toward "on" position, means responsive to operation of a stopping device for a floor and to movement of the car for operating the driving means to move the controller toward its "off" position, means responsive to movement of the controller to approximately its "off" position for opening the clutch to disconnect the controller from its driving means and for operating the centering device to positively center the controller in its "off" position.

26. In an elevator system, a car disposed in a hatchway for serving a plurality of floors, a hoisting motor for the car, a starting means for the motor, a signal device at each floor, stopping devices for the floors, a floor selector having an up carriage and a down carriage mounted thereon for connecting signal and control circuits for the car in accordance with the position of the car with reference to the floors, means for operating the carriages in accordance with the movement of the car, means responsive to an operated stop device and to the movement of the carriages for positively stopping the carriages at their position corresponding to the floor of the operated stop device and for operating the signal device at the floor of the operated stop device, control means responsive to the stopping of the carriages and to the movement of the car for decelerating the hoisting motor for a stop at the floor of the operated stop device in accordance with the movement of the car, means responsive to operation of the control means and to movement of the car for accurately stopping the car at the floor of the operated stop device, and means responsive to the movement of the control means to approximately its "off" position for accurately centering it in its "off" position, whereby the position of the floor selector carriages, the position of the control means and the position of the car are automatically indexed accurately in synchronism at each stop.

27. In an elevator system, a car disposed in a hatchway for serving a plurality of floors, a hoisting motor for the car, a starting means for the motor, a signal device at each floor, stopping devices for the floors, a power means operable by the car in accordance with the movement of the car, an advance motor operable independently of the power means, means responsive to operation of the starting means for starting the advance motor, a floor selector having an up-carriage and a down-carriage movably mounted thereon for operation by the power means and/or the advance motor, for connecting signal and control circuits for the car in accordance with the position of the car with reference to the floors,

means responsive to an operated stop device and to the movement of the carriages for positively stopping the carriages at their position corresponding to the floor of the operated stop device and for operating the signal device at the floor of the operated stop device, control means responsive to operation of the power means and the stopping of the carriages for decelerating the car for a stop at the floor of the operated stop device, means responsive to operation of the control means and to movement of the car for accurately stopping the car at the floor of the operated stop device, and means responsive to the movement of the control means to approximately its "off" position for accurately centering it in its "off" position, whereby the position of the floor selector carriages, the position of the control means and the position of the car are automatically indexed accurately in synchronism at each stop.

28. In an elevator system having a car disposed in a hatchway for serving a plurality of floors divided into an express zone and a high local zone, a hoisting motor for the car, a starting means for the motor, stopping devices for the local zone floors, a floor selector, means for operating the floor selector continuously in synchronism with the car while it travels at normal high speed, means responsive to movement of the car in its express zone for stopping the operation of the floor selector while the car moves through its express zone, means responsive to the approach of the car to the end of its express zone for releasing the floor selector for continuous operation in synchronism with the car while it travels at normal high speed, and means responsive to an operated stop device and to the operation of the floor selector for causing deceleration and stopping of the car at the floor of the operated stop device.

29. In an elevator system, a car disposed in a hatchway for serving a plurality of floors divided into an express zone and a high local zone, a hoisting motor for the car, a starting means for the motor, stopping devices for the local zone floors, a floor lantern for each floor, a floor selector having a frame provided with an express zone and a local zone, an up carriage and a down carriage movably disposed on the frame, means for operating the carriages continuously in synchronism with the car while it travels at normal high speed, means responsive to movement of the car through its express zone for stopping the carriages in the express zone of the frame while the car moves through its express zone, means responsive to the approach of the car to the end of its express zone for releasing the carriages to move in accordance with the movement of the car, means responsive to an operated stop device and to the movement of the carriages for stopping the carriages at their position corresponding to the floor of the operated stop device and for operating the floor lantern at the floor of the operated stop device, and means responsive to the stopping of the carriages and to further movement of the car for first decelerating the hoisting motor for a stop at the floor of the operated stop device and then stopping the car at that floor.

30. In an elevator system a car for serving a plurality of floors divided into an express zone and a high local zone, a hoisting motor for the car, a starting means for the hoisting motor, stop devices for the floors, a power means operable by the car in accordance with the movement of the

car, an advance motor of less power than the power means and operable independently of the power means, a floor selector divided into an express zone and a high local zone and having an up carriage and a down carriage movably mounted thereon, a controller means for decelerating the hoisting motor, differential means connecting the power means, the advance motor, the carriages, and the controller means, means responsive to operation of the starting means for first starting the advance motor and then starting the hoisting motor, whereby the advance motor will operate the differential means to give the carriages a lead ahead of the car and move the controller means toward "on" position, and whereby the power means will operate the differential means to move the carriages in accordance with the movement of the car when it runs at normal speed, a locking means for the controller means, means responsive to movement of the car through its express zone for stopping the carriages in the express zone of the selector, for disconnecting the controller means from the differential means and for actuating the locking means to prevent movement of the controller means while the car moves through its express zone, means responsive to the approach of the car to the end of its express zone for releasing the carriages to move in accordance with the movement of the car, means responsive to operation of a stop device and to movement of the carriages in the local zone of the selector for stopping the carriages to cause the differential means to be operated by the car to move the controller means toward "off" position for decelerating the hoisting motor in accordance with the movement of the car, and means responsive to the movement of the controller means toward "off" position and to movement of the car to within a predetermined distance of the floor of the operated stop device for deenergizing the hoisting motor to stop the car.

31. In an elevator system, a car disposed in a hatchway for serving a plurality of floors, divided into an express zone and a high local zone, a hoisting motor for the car, a starting means for the motor, stopping devices for the local zone floors, a floor selector having a frame provided with an express portion and a local portion, an up carriage and a down carriage slidably disposed on the frame, means for normally operating the carriages in accordance with the movement of the car, an up express lug mounted on the express zone portion of the frame, a down express lug mounted on the express zone portion of the frame, an up pawl movably mounted on the up carriage, a down pawl movably mounted on the down carriage, up cooperating devices mounted on the up carriage and the express portion of the frame and responsive to a predetermined movement of the carriage for operating the up pawl to engage the up express lug to stop the up carriage thereat while the car moves upwardly through the express zone, down cooperating devices mounted on the down carriage and the express portion of the frame and responsive to a predetermined movement of the down carriage for operating the down pawl to engage the down express lug and stop the down carriage thereat while the car moves downwardly through the express zone, and express inductor means disposed on the car and the hatchway wall and responsive to movement of the car for releasing the pawls from their stop position as the car nears the end of an up or a down run through the express zone.

32. In an elevator system, a car disposed in a hatchway for serving a plurality of floors, divided into an express zone and a high local zone, a hoisting motor for the car, a starting means for the motor, stopping devices for the local zone floors, a floor lantern for each floor, a floor selector having a frame provided with an express zone and a local zone, an up carriage and a down carriage movably disposed on the frame, means for operating the carriages in accordance with the movement of the car, a plurality of up contact devices mounted on the local zone of the frame for the local zone floors, a plurality of down contact devices mounted on the local zone of the frame for the local zone floors, an up stop lug mounted on the frame for each local floor, a down stop lug mounted on the frame for each local floor, an up express lug mounted on the express zone of the frame, a down express lug mounted on the express zone of the frame, an up pawl movably mounted on the up carriage, a down pawl movably mounted on the down carriage, up cooperating devices mounted on the up carriage and the express zone of the frame and responsive to a predetermined movement of the carriage for operating the up pawl to engage the up express lug to stop the up carriage thereat while the car moves upwardly through the express zone, down cooperating devices mounted on the down carriage and the express zone of the frame and responsive to a predetermined movement of the down carriage for operating the down pawl to engage the down express lug and stop the down carriage thereat while the car moves downwardly through the express zone, express inductor means disposed in cooperating position on the car and on the hatchway wall and responsive to movement of the car for releasing the pawls from their stop position as the car nears the end of an up or a down run through the express zone, means responsive to an operated stop device and to the movement of the carriages along the contact devices for stopping the carriages at their position corresponding to the floor of the operated stop device and for operating the floor lantern at the floor of the operated stop device, and means responsive to the stopping of the carriages and to further movement of the car for first decelerating the hoisting motor for a stop at the floor of the operated stop device and then stopping the car at that floor.
33. In a floor selector for an elevator car for serving a plurality of floors, a frame, a plurality of tracks disposed on the frame, an up carriage and a down carriage slidably disposed on said tracks, up contact devices mounted on the frame at points spaced apart in proportion to the distances between the floors, down contact devices mounted on the frame at points spaced apart in proportion to the distances between the floors, up stop lugs mounted on the frame at points spaced apart in proportion to the distances between the floors, down stop lugs mounted on the frame at points spaced apart in proportion to the distances between the floors, an up pawl movably mounted on the up carriage for engaging the up stop lug for a floor at which a stop is to be made to stop that carriage at that floor and for operating the up contact devices corresponding thereto, and a down pawl movably mounted on the down carriage for engaging the down stop lug for a floor at which a stop is to be made to stop that carriage for that floor and for operating the down contact devices corresponding thereto.

34. In a floor selector for an elevator car serving a plurality of floors, a frame, a plurality of tracks disposed on the frame, an up carriage and a down carriage slidably disposed on said tracks, contacts mounted on the frame at points spaced apart in proportion to the distances between the floors, a projection mounted on one of said carriages for engaging and operating the contacts for the floors as the carriages are moved in accordance with the movement of the car with reference to the floors, up contact devices mounted on the frame at points spaced apart in proportion to the distances between the floors, down contact devices mounted on the frame at points spaced apart in proportion to the distances between the floors, up stop lugs mounted on the frame at points spaced apart in proportion to the distances between the floors, down stop lugs mounted on the frame at points spaced apart in proportion to the distances between the floors, an up pawl movably mounted on the up carriage for engaging the up stop lug for a floor at which a stop is to be made to stop that carriage at that floor and for operating the up contact devices corresponding thereto, and a down pawl movably mounted on the down carriage for engaging the down stop lug for a floor at which a stop is to be made to stop that carriage for that floor and for operating the down contact devices corresponding thereto.

35. In an elevator mechanism for a car serving a plurality of floors, a hoisting motor for operating the car, a first differential having an input member, an output member, and an input-output member, a power means operable by the car in accordance with the movement of the car for operating the input member, an advance motor of less power than the power means and having its shaft connected for operating the input-output member, a floor selector connected for operation by the output member, a second differential having a driving member connected for operation by the input-output member, and a plurality of controllers disposed for operation in sequence by said second differential to decelerate the hoisting motor when a stop is to be made by the car.

36. In an elevator mechanism for a car serving a plurality of floors, a hoisting motor for operating the car, a power means operable by the car in accordance with the movement of the car, an advance motor of less power than the power means and operable independently thereof, a floor selector, a main controller for decelerating the hoisting motor in coarse steps when a stop is to be made, a leveling controller for decelerating the hoisting motor in fine steps when a stop is to be made, and a pair of cooperating differentials connecting the power means, the advance motor, the floor selector, the main controller and the leveling controller for operating the floor selector to a lead position with reference to the car and for moving the controllers toward "on" position when the advance motor is started, for operating the floor selector in accordance with the movement of the car when the hoisting motor is running at normal speed, and for moving the controllers in sequence to "off" position when the car is to be stopped.

37. In an elevator mechanism for a car serving a plurality of floors, a hoisting motor for operating the car, a power means operable by the car in accordance with the movement of the car, an advance motor of less power than the power means and operable independently there-

of, a floor selector, a main controller for decelerating the hoisting motor in coarse steps when a stop is to be made, a leveling controller for decelerating the hoisting motor in fine steps when a stop is to be made, differential means connecting the power means, the advance motor, the floor selector, the main controller and the leveling controller for operating the floor selector to a lead position with reference to the car and for moving the controllers toward "on" position when the advance motor is started, for operating the floor selector in accordance with the movement of the car when the hoisting motor is running at normal speed, and for moving the controllers to "off" position when the car is to be stopped, and a centering pin for centering the main controller accurately in its "off" position when it is in approximately its "off" position.

38. In an elevator mechanism for a car serving a plurality of floors, a hoisting motor for operating the car, a first differential having an input member, an output member, and an input-output member, a power means operable by the car in accordance with the movement of the car for operating the input member, an advance motor of less power than the power means and having its shaft connected for operating the input-output member, a floor selector having an up carriage and a down carriage movably mounted thereon and connected for movement by the output member for connecting circuits for the car in accordance with the position of the car with reference to the floor, a pawl movably mounted on each carriage for stopping the carriages when a stop is to be made by the car, an electromagnet associated with each carriage for moving its pawl into stopping position, a second differential having a driving member connected for operation by the input-output member, and a plurality of controllers disposed for operation in sequence by said second differential to decelerate the hoisting motor when a stop is to be made by the car.

39. In an elevator mechanism for a car serving a plurality of floors, a hoisting motor for operating the car, a first differential having an input member, an output member, and an input-output member, a power means operable by the car in accordance with the movement of the car for operating the input member, an advance motor of less power than the power means and having its shaft connected for operating the input-output member, a floor selector having an up carriage and a down carriage movably mounted thereon and connected for movement by the output member for connecting circuits for the car in accordance with the position of the car with reference to the floor, a pawl movably mounted on each carriage for stopping the carriages when a stop is to be made by the car, an electromagnet associated with each carriage for moving its pawl into stopping position, a second differential having a driving member connected for operation by the input-output member, and having a first driven member and a second driven member, a main controller disposed for operation by said first driven member to decelerate the hoisting motor in coarse steps when a stop is to be made, and a leveling controller connected for operation by the second driven member for decelerating the hoisting motor in fine steps when a stop is to be made.

40. In an elevator mechanism for a car serving a plurality of floors, a hoisting motor for operating the car, a first differential having an input member, an output member, and an input-

output member, a power means operable by the car in accordance with the movement of the car for operating the input member, an advance motor of less power than the power means and having its shaft connected to the input-output member, a floor selector having an up carriage and a down carriage movably mounted thereon and connected for movement by the output member for connecting circuits for the car in accordance with the position of the car with reference to the floors, a pawl movably mounted on each carriage for stopping the carriages when a stop is to be made by the car, an electromagnet associated with each carriage for moving its pawl into stopping position, a second differential having a driving member connected for operation by the input-output member, and having a first driven member and a second driven member, a main controller disposed for operation by said first driven member, to decelerate the hoisting motor in coarse steps when a stop is to be made, a leveling controller connected to the second driven member for decelerating the hoisting motor in fine steps after the main controller is moved to its "off" position, when a stop is to be made, and a controller brake mechanism for limiting the operation of the controllers to a predetermined order when the car is to be started and to another predetermined order when the car is to be stopped.

41. In an elevator mechanism for a car serving a plurality of floors, a hoisting motor for operating the car, a first differential having an input member, an output member, and an input-output member, a power means operable by the car in accordance with the movement of the car for operating the input member, an advance motor of less power than the power means and having its shaft connected to the input-output member, a floor selector having an up carriage and a down carriage movably mounted thereon and connected for movement by the output member for connecting circuits for the car in accordance with the position of the car with reference to the floors, a pawl movably mounted on each carriage for stopping the carriages when a stop is to be made by the car, an electromagnet associated with each carriage for moving its pawl into stopping position, a second differential having a driving member connected for operation by the input-output member, and having a first driven member and a second driven member, a main controller disposed for operation by said first driven member, to decelerate the hoisting motor in coarse steps when a stop is to be made, a leveling controller connected to the second driven member for decelerating the hoisting motor in fine steps after the main controller is moved to its "off" position when a stop is to be made, a main controller brake, a leveling controller brake, and an electromagnet for operating the brakes to select the controller to be operated by the driven members of the second differential.

42. In an elevator mechanism for a car serving a plurality of floors, a hoisting motor for operating the car, a first differential having an input member, an output member, and an input-output member, a power means operable by the car in accordance with the movement of the car for operating the input member, an advance motor of less power than the power means and having its shaft connected to the input-output member, a floor selector having an up carriage and a down carriage movably mounted thereon and connected for movement by the output

member for connecting circuits for the car in accordance with the position of the car with reference to the floors, a pawl movably mounted on each carriage for stopping the carriages when a stop is to be made by the car, an electromagnet associated with each carriage for moving its pawl into stopping position, a second differential having a driving member connected for operation by the input-output member, and having a first driven member and a second driven member, a main controller disposed for operation by said first driven member to decelerate the hoisting motor in coarse steps when a stop is to be made, a leveling controller connected to the second driven member for decelerating the hoisting motor in fine steps when a stop is to be made, a main controller brake, a leveling controller brake, an electromagnet for operating the brakes to select the controller to be operated by the second differential, a clutch for connecting and disconnecting the main controller and the first driven member, a centering device for accurately centering the main controller in its "off" position, an electromagnet for opening the clutch and operating the centering device when the main controller reaches its "off" position, and means for limiting the "on" movement of the main controller to stall the advance motor, so that the power means will drive the first differential to move the carriages while the car is running at normal speed.

43. In an elevator system having a car for serving a plurality of floors, a selector movable substantially in accordance with car motion when travelling at high speed; means for causing a stop operation of said selector, a coarse speed control device associated with said selector and normally in full speed position, means responsive to a stop operation of said selector to cause said control device to move to a predetermined low speed position in accordance with car motion; a fine speed controller; transfer means responsive to the position of said car when said car is at a predetermined distance from said floor to render said coarse speed control device ineffective and to render effective said fine speed controller, and a resetter responsive to actuation of the transfer means for resetting said coarse speed controller in a predetermined position.

44. In an elevator system having a car for serving a plurality of floors, a starting means for the car, a stopping means for the car, a floor selector including a control device operable substantially in accordance with the movement of the car in one direction during up operation of the car and in a reverse direction during down operation of the car for decelerating the car, a centering mechanism operable for moving the control device to a predetermined position independent of the position of the car, and means responsive to a predetermined position of the car for operating the centering mechanism to accurately align said control device to the first-named predetermined position.

45. In an elevator controller for a car operable past a plurality of floors and for stopping said car at said floors in response to actuated floor push buttons, the combination of starting means for said car and stopping means; a floor selector comprising coarse speed reducing means and fine speed reducing means, both operable in response to car motion, means responsive to the actuation of a push button at a floor and the approach of said car to a predetermined distance

of said floor for rendering effective said coarse speed reducing means, inductor means mounted on the car and responsive to the approach of said car to a predetermined distance of said floor for rendering ineffective said coarse speed reducing means and for rendering effective said fine speed reducing means, and a resetter responsive to operation of the inductor means for actuating the coarse speed reducing means independently of the car to a predetermined position.

46. In a elevator system having an elevator car for serving a plurality of floors, a starting means for the car, a stopping means for the car, a floor selector including a control device operable in accordance with the movement of the car for controlling the speed of the car, a resetter operable into and out of engagement with the control device, said resetter when in engagement with the control device positively forcing the control device into a predetermined position, and means effective upon completion of an operation of the control device for actuating the resetter into engagement with the control device to position the control device in said predetermined position.

47. In an elevator system, an elevator car for serving a plurality of floors, a hoisting motor for the car, and a regulator for regulating move-

ment of the car, said regulator comprising a controller displaced from the car for decelerating the car from a traveling speed to a lower speed as the car approaches a floor at which it is to stop, coupling means coupling the controller for operation in response to movement of the car, a control unit on the car, a control device for each of the floors served by the car cooperating with the control unit when in operating condition for effecting a control operation, the regulator including means responsive to a control operation of the control unit and the control device at a floor at which the car is to stop for taking control of the car after it has reached the lower speed a predetermined distance from a floor at which the car is to stop in order to bring the car to a stop from the lower speed accurately at the desired floor.
